ABSTRACT: An automatic pocket blank sewing machine has been provided which automatically separates and feeds a single pocket blank ply, a single facing patch ply, mates these two, sews, removes the sewn workpiece for folding the facing patch to hide its stitch line, folds the longitudinal edge seams (for subsequent sewing), folds the pocket blank ply to form a pocket pouch and then removes and stacks the folded pocket blank pouch.

POCKET BLANK FORMING MACHINE

This invention relates to a pocket-blank-forming machine; more particularly, this invention relates to a pocket-blank-forming machine suitable for garments, of which men's pants back-pocket-blank-forming machine is illustrative.

Pockets such as for man's pants are generally formed from a pocket blank to which a facing patch is sewn. This facing patch is exposed through a pocket opening. In order to cover the facing patch seam, this patch is folded. Thereafter, the longitudinal edges of the pocket blank are folded inwardly for a width of about three-eighths inch and then the pocket blank folded onto itself with a longer edge exposing the facing patch, to form the shape of the pocket pouch.

In this form and in a different machine, this pocket blank is sewn along the edges thereof to form a back pocket pouch for subsequent incorporation of the same in a garment such as a man's pants leg.

In the prior art method of practicing this manufacturing sequence, a number of steps have been proposed to form a pocket blank. Although for the most part these steps are being formed with aid of various and different machines now available to the trade, these steps, even when individually combined, have required excessively wasteful motions as well as being inefficient to accomplish the various manufacturing steps.

Moreover, in the prior art the various sequential manufacturing steps which may be carried out on a pocket blank have been performed in a disjointed manner requiring excessive number of wasteful machine steps and excessive number of material-handling steps which demand careful handling by skilled operators of the various machines to manufacture the pocket blank in a form such as it may be sewn around the periphery thereof.

Although a number of prior art machines have been proposed for carrying out various steps in a sewing sequence and a number of work-feeding and work-removing devices have been proposed as suitable for manufacturing a number of identical or substantially identical garments, these workpiece-handling devices are unsuitable because the almost infinitely repetitive work cycle requires specific and particular machinery. Even though alleged to be suitable for a number of different workpieces, these blank-forming machines do not perform in a satisfactory manner and are considerably more complex and unduly complicated. These machines do not provide for normal flow of the workpiece for action by the machine thereon. Furthermore, these machines do not carry out the work sequence steps in a manner which allows the workpiece to flow freely through the machine. Consequently, the prior art machines have failed for a number of reasons to provide devices to fashion into a back pocket blank a pocket blank ply with a facing patch sewn to it for subsequent sewing and formation of a pocket pouch.

According to the present invention, a novel machine has been provided which not only picks up a facing patch fabric and a pocket blank fabric ply and properly relates the pocket blank to its facing patch, transfers the facing patch for sewing onto the pocket blank, but also thereafter sequentially carries out the pocket-blank-forming steps by removing the pocket ply with its sewed on facing patch from a specifically designed sewing machine, folding the facing patch to cover the facing patch sewn, as well as folding the edges around the sides of the pocket blank, folding the pocket to form the pocket blank to the extent it is necessary to have a specified pouch and finally removing this pocket blank from the machine in a manner suitable for its subsequent sewing in another machine around the periphery thereof.

The novel pocket-blank-forming machine accomplishes these steps in an operator-unaided sequence in a manner such that the freely flowing workpieces, i.e. a facing patch and a single ply are joined and produced in a pocket blank by merely introducing the various components in an automatically operated machine which performs stepwise work sequences.

As a result of the present invention, the production of the back pocket blank has been nearly doubled from that achievable by previous art devices used to form these back pocket

blanks; and the carefully sequenced novel machine carries out the complex operations in a superior manner, forming the back pocket blanks by eliminating numerous steps which heretofore have been required when carrying out the individual operator controlled sequences on a piecemeal production basis.

Moreover, according to the present invention, a novel facing patch ply pickup and a novel single pocket blank ply separation and transfer devices have been incorporated in this machine. These devices allow the ready pickup and transfer of fabric plies, and may be independently useful outside this pocket-blank-forming machine.

Thus, the ply pickup subcombination is useful for fabric ply separation, i.e. one ply from the other, and the transfer of the separated ply to a conveying means for subsequent use in other, properly work-sequenced apparatus.

For example, one of the novel subcombinations associated with the present apparatus provides for separation of a workpiece blank from a stack of piles, and transfer of this ply, in reverse face fashion, for subsequent handling and removal from the transfer device in an especially facile and simple manner.

Another novel ply separation device has been disclosed which separates fabric plies from a stack by twisting the top ply into a ply-advancing means and then disengages the stack from the twisting means.

In reference to the foregoing and to the drawings, these drawings illustrate the novel apparatus and the methods associated therewith, wherein the various figures also illustrate the various subcombinations and wherein:

FIG. 1 shows a die cut or otherwise cut fabric ply from which a pants back pocket blank is formed;

FIG. 2 shows a facing patch;

FIG. 3 shows the placement of the facing patch on the pocket blank ply and the stitching line for it;

FIG. 4 shows the facing in a folded position on a pocket blank;

FIG. 5 shows the folded edges along the longer sides of a pocket blank ply;

FIG. 6 shows a folded pocket blank;

FIG. 7 shows an isometric view of the novel machine;

FIG. 8 shows a top view of the machine isometrically illustrated in FIG. 7 with some of the details which have been illustrated elsewhere removed for sake of clarity;

FIG. 9 shows in perspective facing ply pickup device labeled as "twist pickup device";

FIG. 10 shows a section along lines 10—10 of this twist pickup device;

FIG. 11 shows a top view of the twist pickup device;

FIG. 12 shows a schematic drawing of a pneumatic circuit employed with the twist pickup device;

FIG. 13 shows the electrical circuit which controls the twist pickup device with the delay circuit identified as FIGS. 13b to 13d;

FIG. 14 illustrates a single ply pickup and transfer device in an isometric view;

FIG. 15 shows a section 15—15 of the single ply pickup and transfer device of FIG. 14 with FIGS. 15a, 15b, and 15c showing the transfer device in three positions in the transfer sequence of the single fabric ply;

FIG. 16 shows a side view of the single ply pickup and transfer device with associated mechanism, air tubes and switch means as well as a stack of plies;

FIG. 17 shows the front view partially in section illustrating the pickup and transfer device mechanism associated with the advance and take up of an adhesive tape used as the fabric pickup means;

FIG. 18 shows a section view of the lines 18—18 of FIG. 17 illustrating the gearing associated with the pickup means;

FIG. 19 shows the top view of the pickup and transfer device of FIG. 14 but without the means associated with adhesive tape pickup of the fabric ply;

FIG. 20 shows an electrical control circuit for the single ply pickup and transfer device;

FIG. 21 shows a facing-patch-mating device by means of which a facing patch is placed on a pocket blank fabric;

FIG. 22 shows a cross section along line 22—22 of FIG. 21 of the facing-patch-mating device, a cross section of the sewing machine in cooperation with the facing-patch-mating device as well as a pocket-blank-advancing means for sewing the facing patch to this blank and an end view of a gear train employed for reciprocally moving the sewing table;

FIG. 23 shows a top view of the sewing machine with the worktable and a unique presser foot employed in the sewing of the facing patch to the pocket blank ply as well as the placement of the gear train in relationship to the sewing machine table;

FIG. 24 shows a front view of the sewing machine along line 24—24 of FIG. 22 illustrating the location of the presser foot guide rail and the means used for moving the worktable left and right as well as the gear and clutch relationship, the return means, etc.,

FIG. 25 shows the front view of the gear train and rack for moving the sewing machine table;

FIG. 25a shows the electric clutch interposed in the gear train in a disengaged position;

FIG. 25b shows the electric clutch interposed in the gear train in an engaged position;

FIG. 26 shows a front view of a rake device used for removing the sewn workpiece from the sewing machine table;

FIG. 27 shows the electrical circuits associated with the devices illustrated in FIGS. 21 to 26 and their controlled interrelationship;

FIG. 28 shows an isometric view of the facing folder device; according to this view, the pocket blank with the facing sewn to it travels from left to right;

FIG. 29 shows a simplified cross section of the facing folder device along lines 29—29 of FIG. 28;

FIG. 30 shows an electrical circuit means for the facing folder unit depicted in FIGS. 28 and 29;

FIG. 31 shows the top view of the side edge folding and pressing device;

FIG. 32 shows the side-seam-forming die illustrated in an isometric view;

FIG. 32a shows an isometric view of gate, pulley and "presser-down" microswitch illustrated in FIG. 31;

FIGS. 33, 33a and 33b show an isometric, a top and a side view, respectively;

FIG. 34 shows a simplified cross section of the side folding and pressing device along line 34—34 of FIG. 31;

FIG. 35a to 35h show a schematic folding and pressing sequence associated with the pocket blank side edge seam forming;

FIG. 36 shows an electrical circuit means for the side edge seam folding and pressing device illustrated in FIGS. 31 to 35h;

FIG. 37 shows an isometric view of the pocket blank folder and presser device, as well as a stacker device;

FIG. 38 shows a schematic drawing of the operating sequence in the folding and pressing of the pocket blank;

FIG. 39 shows the electrical circuit associated with the device used for folding and pressing the pocket blank and shown in FIGS. 37 to 38;

FIG. 40 shows a simplified illustration of the folded pocket blank as it is removed from the machine and as an end view along line 40—40 of FIG. 37;

FIG. 41 illustrates the belt conveyor along line 41—41 of FIG. 8 as a side view showing finished pocket blanks as these are stacked on the conveyor; and

FIG. 42 illustrates an electrical circuit as means for controlling the stacker and belt conveyor devices.

In accordance with the invention herein and in reference to FIG. 7 which shows the isometric view of the machine as well as FIG. 8 which shows the top view of the novel machine intended to accomplish the complete sequence of forming a back pocket blank, the work sequence is initiated by a proper signal from the sewing machine unit 130 to the twist pickup device 39 as discussed in the section pertaining to the electri-

cal description. The twist pickup device is shown in FIGS. 9 to 11. Thus, a facing patch B as shown in FIG. 2 is picked up by the device 39 and sent along conveyor rollers 19.

Simultaneously, a signal to the back pocket blank pickup and transfer device 40 from sewing machine unit 130 causes to be forwarded along the conveyor rollers 66 a single fabric ply A from which the pocket blank is formed. The ply A is captured by means provided therefor on the sewing machine table 134. The facing patch B is placed on the back pocket blank held on the table 134 by the facing-mating device 100. After the sewing of the facing patch B to the pocket blank A by the sewing machine 131, the sewn pocket blank is removed by a rake device 180, forwarded along the conveyor 229 to the patch-folding device 200 which folds the facing patch B as shown in FIG. 4.

Thereafter, the back pocket blank A is pressed along the longitudinal edges in the edge forming and pressing device 250 which is also illustrated in FIGS. 31 to 36. To obtain the pocket blank B as shown in FIG. 5, the edges are folded and pressed in a sequence as shown in FIG. 35a to 35h. The thus formed and pressed pocket blank is then forwarded to the lengthwise pocket folding and pressing device 330 where the pocket blank B is folded lengthwise upon itself to the desired proportions as shown in FIG. 6. This folded pocket blank is forwarded to the stacker device 370 from which the pocket is deposited on the belt conveyor 390.

Thus, referring back to the FIGS. 1 to 6 in which the back pocket blank is illustrated in its various stages of forming by the machine, these stages and the combination of machine elements and devices can easily be envisioned by reference to FIG. 8 as well as the isometric representation of the machine illustrated in FIG. 7.

TWIST PICKUP DEVICE 39

a. Mechanical Means

Turning now to each of the individual devices previously identified and which devices will be described and disclosed hereinafter more amply, reference is first made to FIGS. 9 to 13d in which the twist pickup device 39 and its control means are illustrated. In this discussion the electrical control means will be covered as the last item.

A worktable 9 illustrated in FIG. 9 and shown in cross section in FIG. 10, holds a stack 24 of facing patches. This table 9 is actuated by means of a properly timed pneumatic pressure-activated piston cylinder 10 which is reciprocated along a piston shaft 11 by means of air introduced under pressure through opening 21; piston 10 is guided along the piston shaft 11 by means of a ball bearing friction-reducing device 22. In order to obtain a constant pressure against the serrated twist head 1 with the stack 24, the pneumatic pressure in cylinder 10 is kept on for the desired period by a bleed means 23 in the form of a small circumferentially peripheral opening. This means accomplishes the pressure-regulating function. By means of electrical control circuit further described herein, a pressure relief or exhaust valve 27 shown in FIG. 12 allows the table 9 to drop substantially simultaneously when wheel 13 has captured the facing patch twisted in its reach by the twist head 1.

Amplifying the previous, upon contact of the table 9 at the maximum up stroke of the pressure activated piston cylinder 10, twist head 1, (properly activated by the devices discussed in the electrical section hereof, and which is a serrated teeth carrying cup designated as a twist head and sold as a conventional home workshop large diameter hole-cutting bit), makes a 90° turn and allows the facing patch to be introduced on the conveyor apron 14 over an optional idler roller 31 (shown in FIG. 10, not shown in FIG. 7, 10 and 11) for engagement with the puller wheel 13 for conveying along rollers 19. As shown in FIG. 7, these rollers may also be replaced by a continuous belt 19e. These conveyor rollers 19 are mounted in conveyor roller frame 19a and may be intergeared with intergears 19c or chain driven.

The twist head 1 acts as a ply separator which separation normally is very hard to achieve because of the inherent adhesion characteristics of textile or fabric plies one to another. The imparted twisting movement thus separates the fabric plies one from the other without allowing an additional ply to be sent along conveyor rollers 19.

The twist head 1 is driven clockwise by a motor 6 placed on a top plate 1c on a frame 1b which in turn is mounted on frame 1a holding the twist pickup unit. A suitable motor is one which has very low coasting characteristics. A number of makes of these motors are available on the market. The width of the table 9 is adjusted between two sideplates 7 by means of a restraining plate 8 which folds one of the sideplates 7 and allows it to be moved along the adjustable holding bars to which plate 8 is affixed. An adjustable restraining piece is 12 mounted on the adjustable holding bars 8a. This restraining piece which protrudes over the worktable 9 and the workpiece stack 24 stops the upward movement of the workpiece stack 24 when the piston 10 is being urged upwardly along the piston shaft 11. As previously mentioned, the small opening 23 of about 0.02 inches in width on each side of the shaft 11 or circumferentially therearound allows the air pressure built up in the piston to bleed through this opening 23 and through the friction-reducing linear bearing 22 thus maintaining almost a constant force of the worktable 9 against the serrated twister head 1 as controlled and restrained by the restraining piece 12. This restraining piece also aids in preventing the pickup of more than one facing ply. The twister head turns through 90° clockwise movement and its degree of twisting is governed by the electrical means further discussed herein. At about the end of the twist period, an exhaust valve 27 for piston 10 is opened and the stack moves downwardly at a rate controlled and adjustable by the back pressure of valve 27. As the twisted ply is turned through 90°, it is engaged by a puller wheel 13 rotating on shaft 13a, at the end of lever frame 13b attached to pivot shaft 13c which is activated by pneumatic cylinder 16 pivoting from cylinder-holding frame 16a. The puller wheel 13 is provided with elastomeric ribs or O-ring type of belts 15 which surround the circumferentially protruding double ribs of puller wheel 13 to give better friction characteristics for disengaging the facing ply B from the serrated edge 1 and to allow the facing ply to be conveyed onto the conveyor rollers 19.

The puller wheel 13, mounted on shaft 13a, is driven by means of a pulley 33 which in turn is driven by belt 34. The last derives its power from a conveyor roller 19 having a conveyor roller shaft extension 35, and a pulley 32 mounted thereon. The conveyor rollers in turn are driven by motor 36 via belt 36a driving a pulley 36b.

After a properly timed sequence, discussed below, a spring 17 retracts the pivoted puller wheel 13. The puller wheel 13 is driven down onto the idler roller 31 (optional) which roller is not part of the conveyor, by air cylinder 16 pivotally articulated on frame 16a so that upon the downward stroke the puller wheel 13 may be properly engaged with the idler roller 31.

The pneumatic operation of the twist pickup device is illustrated in FIG. 12 in which the stack release operation previously described is schematically shown as item 25 the stack release solenoid valve being illustrated as 26. The exhaust valve 27 is first for the purpose of disengaging the stack from the twister head 1 and regulator 20 controls the relative velocity of the stack release cylinder. Also, a second pressure regulator 28 is inserted in a shop air supply which air is filtered in a filter device 30 and admitted to cylinder 16 by means of a solenoid controlled valve 29.

A representative pneumatic system for pneumatically operated cylinders, employed in various sections of this machine, is also shown in FIG. 12.

After ply B thus has been separated and conveyed from the pickup site and is moving on conveyor roller 19, the stack release solenoid valve 27 again is shut off which repeats this cycle by moving the table 9 upwardly. This event at the same

times causes the puller wheel solenoid valve 29 to be deenergized which also completes the cycle.

The facing ply B is generally cut by means of a die.

b. Electrical Control Means For Twist Pickup Device 39

5 The electrical control means as represented by the electrical circuit for the twist pickup device 39 is shown as item 700 in FIG. 13a. Delay circuits which are identified in FIG. 13a as 710, 711 and 712 are illustrated in FIGS. 13b to 13d. The mechanical operating cycle of this device was described above. The operation of the control circuit 700 will now be explained by describing what happens at each step in its operating cycle, by reference to the previously detailed mechanical means.

15 INITIAL CONDITIONS PRIOR TO START OF OPERATING CYCLE

Standard alternating current is applied to AC power terminal 701 and ground terminal 703. Twenty-six volts DC is applied to DC power terminal 702 and ground terminal 703. The following circuit conditions exist:

1. Relay 713 is deenergized.
2. Input terminal 717 of first timer circuit 710 is grounded through relay 713. This places first timer circuit 710 in a hold mode with positive DC voltages at output terminals 718 and 719. The operation of first timer circuit 710 will be described hereinafter.
3. The positive voltage at output terminal 718 causes triac 724 to conduct. Stack release solenoid valve 26 which closes exhaust valve 27 is thereby energized through triac 724 causing the stack to be held up against the twister head 1.
4. The positive DC voltage at output terminal 719 places second timer circuit 711 in a hold mode with output terminal 721 at ground potential. The operation of second timer circuit 711 will be described hereinafter.
5. The ground potential at output terminal 721 causes triac 725 to be nonconducting. Capacitor 727 prevents triac 725 from energizing due to AC transients. Puller wheel solenoid valve 29 is therefore deenergized.
6. The positive voltage at output terminal 719 places third timer circuit 712 in a hold mode. A positive DC voltage will be present at output terminal 723, when the ground path to start terminal 704 is completed. The operation of third timer circuit 712 will be described hereinafter.

START OF OPERATING CYCLE

The operating cycle is initiated by completing the ground-path to start terminal 704. This is accomplished by a signal from output terminal 904 of electrical control circuit 900, in a manner to be described hereinafter. This provides a ground-path for relay 713, causing it to be energized by the positive DC voltage at output terminal 723 of third timer circuit 712, with the following results:

1. Relay 713 latches in its energized state through its internal groundpath.
2. The groundpath to terminal 717 of first timer circuit 710 is opened by relay 713, causing first timer circuit 710 to begin its timing mode.
3. Twister motor 6 is energized through relay 713 and triac 724.

65 END OF FIRST TIMER CIRCUIT TIMING INTERVAL

The timing interval of first timing circuit 710 shown in FIG. 13b corresponds to the time required for the twister motor 6 to rotate 90°. At the end of this time interval, first timer circuit 710 switches, causing output terminals 718 and 719 to assume ground potential, with the following results:

1. Triac 724 assumes a nonconducting state, thereby deenergizing the twister motor 6 and the stack release solenoid valve 26. Capacitor 726 prevents triac 724 from energizing due to AC transients.

2. Input terminal 720 of second timer circuit 711 assumes a ground potential causing second timer circuit 711 to begin its timing mode.
3. Input terminal 722 of third timer circuit 712 assumes a ground potential causing third timer circuit 712 to begin its timing mode.

END OF SECOND TIMER CIRCUIT TIMING INTERVAL

The timing interval of second timing circuit 711 shown in FIG. 13c corresponds to the time required to release the ply between the stack and the twister. At the end of this time interval, second timer circuit 710 switches, causing output terminal 721 to assume a positive DC voltage. This causes triac 725 to conduct, thus energizing the puller solenoid through triac 725.

END OF THIRD TIMER CIRCUIT TIMING INTERVAL

The timing interval of third timing circuit 712 shown in FIG. 13d corresponds to the time interval from the end of the timing interval of first timer circuit 710 to the time the ply has been conveyed away. At the end of this time interval, third timing circuit 712 switches, causing output terminal 723 to assume ground potential thereby deenergizing relay 713 causing all circuitry to return to the initial conditions. Diode 728 protects third timer circuit 712 from the back e.m.f. generated when relay 713 deenergizes. The twist pickup device 39 has now mechanically and electrically completed its cycle.

FIRST TIMING CIRCUIT 710

The electrical circuit for first timing circuit 710 is illustrated in FIG. 13b. The operating modes of first timing circuit 710 were related above in the description of the twist pickup device 39. The operation of first timing circuit 710 will now be explained by describing what happens in each mode of its operation.

HOLD MODE

Twenty-six volts DC is applied between DC input terminal 714 and ground. When input terminal 717 is grounded, the following results:

1. Resistor 733, variable resistor 732, and resistor 730 form a series circuit. The voltage at the junction of resistor 730 and variable resistor 732 is less than the zener voltage of zener diode 734, causing zener diode 734 to be nonconducting.
2. Transistor 736 has no base drive and is therefore biased into nonconduction by resistor 735.
3. Transistor 739, in an emitter follower configuration, is biased into conduction through resistor 737 and resistor 738.
4. Positive DC voltages are present at output terminals 718 and 719, due to the flow of the emitter current of transistor 739 through emitter resistors 740 and 741.

TIMING MODE

First timer circuit 710 enters its timing mode when the groundpath to input terminal 717 is opened, with the following results:

1. Resistor 733, variable resistor 732 and capacitor 731 form a series RC circuit. Capacitor 731 charges at a rate determined by the setting of variable resistor 732.
2. After a period of time, corresponding to the timing interval of first timing circuit 710, the voltage of capacitor 731 reaches the zener voltage of zener diode 734. This causes the circuit to switch as follows:
  - a. Zener diode 734 conducts, providing base drive to transistor 736, causing it to conduct.
  - b. The voltage at the junction of resistors 737 and 738 is thereby reduced, depriving transistor 739 of base drive.
  - c. Transistor 739 assumes a nonconducting state, terminating the current flow through emitter resistors 740 and 741.

- d. Output terminals 718 and 719 therefore assume a virtual ground potential.

When input terminal 717 is once again grounded, capacitor 731 will discharge through resistor 730, causing all circuitry to return to its hold mode condition. First timer circuit 710 is thus reset.

SECOND TIMING CIRCUIT 711

The electrical circuit for second timing circuit 711 is illustrated in FIG. 13c. The operating modes of second timing circuit 711 were related above in the description of the twist pickup device 39. The operation of second timing circuit 711 will now be explained by describing what happens in each mode of its operation.

HOLD MODE

Twenty-six volts DC is applied between DC input terminal 715 and ground. When a positive DC voltage is applied to input terminal 720, the following results:

1. Transistor 751 is biased in a conducting state by the base drive current through resistor 750.
2. Resistor 755, variable resistor 754, resistor 752 and transistor 751 form a series circuit. The voltage at the junction of resistor 752 and variable resistor 754 is less than the zener voltage of zener diode 756, causing zener diode 756 to be nonconducting.
3. Transistor 758 has no base drive and is therefore biased into nonconduction by resistor 757. Capacitor 759 prevents transistor 758 from firing due to unwanted transients or noise.
4. Transistor 762, in a normal amplifier configuration, is biased into nonconduction by resistors 760 and 761.
5. Output terminal 721 assumes a virtual ground potential due to the absence of emitter current through emitter resistors 763 and 764.

TIMING MODE

Second timer circuit 711 enters its timing mode when the positive DC voltage is removed from input terminal 720, with the following results:

1. Resistor 755, variable resistor 754 and capacitor 753 form a series RC circuit. Capacitor 753 charges at a rate determined by the setting of variable resistor 754.
2. After a period of time, corresponding to the timing interval of second timing circuit 711, the voltage of capacitor 753 reaches the zener voltage of zener diode 756. This causes the circuit to switch as follows:
  - a. Zener diode 756 conducts, providing base drive to transistor 758, causing it to conduct.
  - b. The voltage at the junction of resistors 760 and 761 is thereby reduced, providing base drive to transistor 762.
  - c. Transistor 762 assumes a conducting state, causing current to flow through emitter resistors 740 and 741.
  - d. Output terminal 721 therefore assumes a positive DC voltage.

When a positive DC voltage is reapplied to input terminal 720, transistor 751 will assume a conducting state, thereby discharging capacitor 753. All circuitry will return to its hold mode condition. Second timer circuit 711 is thus reset.

THIRD TIMING CIRCUIT 712

The electrical circuit for third timing circuit 712 is illustrated in FIG. 13d. The operating modes of third timing circuit 712 were related above in the description of the twist pickup device 39. The operation of third timing circuit 712 will now be explained by describing what happens in each mode of its operation.

HOLD MODE

Twenty-six volts DC is applied between DC input terminal 716 and ground. When a positive DC voltage is applied to input terminal 722, the following results:

1. Transistor 771 is biased in a conducting state by the base drive current through resistor 770.
2. Resistor 775, variable resistor 774, resistor 772 and transistor 771 form a series circuit. The voltage at the junction of resistor 772 and variable resistor 774 is less than the zener voltage of zener diode 776, causing zener diode 776 to be nonconducting.
3. Transistor 778 has no base drive and is therefore biased into nonconduction by resistor 777.
4. Transistor 781 is in an emitter follower configuration, with the emitter load path supplied by the coil of relay 713. Transistor 781 is biased by resistors 779 and 780, so that it will conduct when the emitter load path is completed.
5. A positive DC voltage will thus be present at output terminal 723, when the emitter load path is completed.

TIMING MODE

Third timer circuit 712 enters its timing mode when the positive DC voltage is removed from input terminal 722, with the following results:

1. Resistor 775, variable resistor 774 and capacitor 773 form a series RC circuit. Capacitor 773 charges at a rate determined by the setting of variable resistor 774.
2. After a period of time, corresponding to the timing interval of third timing circuit 712, the voltage capacitor 773 reaches the zener voltage of zener diode 776. This causes the circuit to switch as follows:
  - a. Zener diode 776 conducts, providing base drive to transistor 778, causing it to conduct.
  - b. The voltage at the junction of resistors 779 and 780 is thereby reduced, depriving transistor 781 of base drive.
  - c. Transistor 781 assumes a nonconducting state.
  - d. Output terminal 723 therefore assumes a virtual ground potential.

When a positive DC voltage is reapplied to input terminal 722, transistor 771 will assume a conducting state, thereby discharging capacitor 773. All circuitry will return to its hold mode condition. Third timer circuit 712 is thus reset.

SINGLE PLY SEPARATOR AND TRANSFER DEVICE 40

a. Mechanical Means

In reference to FIGS. 14 to 20, the single ply pocket blank pickup and transfer unit also identified in FIGS. 7 and 8 as 40 will now be discussed in respect to its operation, the mechanical means, and electrical control means thereof.

This device, which forwards ply A to the sewing machine, consists of a worktable 41 which holds a stack 72 of die cut or otherwise cut back pocket blanks A placed on the worktable 41 which is supported by racks 42 driven vertically upwardly by pinions 43 mounted on shaft 76 driven by motor 46. The racks 42 are guided by rack guides 44 such as low-friction roller bearings.

When the motor 46 is activated, it lifts upwardly the table 41 with the stack 72 of plies, the top ply to be engaged by a tape 49 guided over tape guide and pickup head roller 58. A spring 45 assists the lifting of the worktable 41.

The single ply transfer device itself, which has been designated as 47, is rotated in clockwise direction by motor 48 which drives incrementally the tape 49 by rotating the transfer device housing 59 which is rigidly attached to shaft 50. An inner, fixed shaft 51 to which is attached a worm 53 is stationary and this worm 53 drives worm gear 54 (which has a cutout space 53 for it provided in shaft 50) which worm gear 54 in turn is driving a pinion gear 55. The pinion gear 55 in turn is driving a tape takeup reel gear 56 which on the other end of its shaft 56a has a tape takeup reel 56b. As the gear 56 is driven during the rotation of housing 59, it advances over the guide roller 58, the tape 49 from tape supply reel 57. In a manner well known in the art by appropriately gearing the worm 53, the worm gear 54, the pinion 55, and the takeup reel gear 56, suitable speed of the tape 49 may be obtained. Thus,

it has been found that a tape advance of one thirty-second inch during one revolution is sufficient.

The takeup reel 56b and supply reel 57 which holds the tape is placed on the opposite side of the housing 59 from the takeup reel drive gear 56. The takeup reel 56b and the gear 54, 55, 56 as well as the supply reel 57 are carried by shaft fixedly attached to housing 59, as is the rotating sleeve 50.

FIG. 18 illustrates this relationship of the gears and reels. Bushing or rotating sleeve or shaft 50 is also attached fixedly to frame 59. The rotating pocket transfer unit shaft 50 is driven by the motor 48.

The rotating shaft 50 also carries on the extension thereof as shown in FIG. 14, a stop cam 78, an "up air blast" cam 79, a puller cam 80 and a "side air blast" cam 90. (The last is not shown but is similar to others).

Upon rotating, the appropriately placed cams activate their corresponding switches such as stop cam switch 81, "up blast" cam switch 82, puller cam switch 83 or "side air blast" cam switch 91 (not shown). The pickup and transfer unit is enshrouded on one side thereof, i.e. on the side, which because of the clockwise rotation carries the pocket blank, with a sheet metal pocket blank guide 60.

The motor 48 is carried in frame 40a for the pickup and transfer device. Double ribbed puller wheel 61 activated by puller cam 80 and switch 83 (as further explained in the discussion pertaining to the electrical control means) through a puller wheel solenoid valve 62 activated pneumatic cylinder 95 engages the pocket blank carried by the tape 49 on the tape head roller 58 and which has placed the edge of the pocket blank A over the stripper plate 69.

The puller wheel 61 sends the pocket blank onto rotating conveyor rollers 66 when the puller cylinder 95 brings down the fulcrum arms 63 which carry the puller wheel 61 on puller shaft 89. The fulcrum arms are engaged at one end thereof to a pivoting shaft 85a and constantly driven by a puller wheel belt 84 which derives its power from an extension of a shaft from one of the conveyor rollers 66 over pulleys 84a and b. A puller wheel spring 64 is used to bring the puller wheel 61 down on the pocket blank as the puller wheel cylinder 95 is used for the upstroke, i.e. disengagement of wheel 61. Through appropriately geared pulleys 84a and b the speed of the puller wheel 61 may be selected which will suitably disengage the pocket blank from the tape 49 for its conveyance along the conveyor rollers 66.

The operating cycle of the single ply pocket transfer device is initiated by rising the stack of clothes as shown in FIG. 16 until the stack makes contact with the tape 49. The stack of clothes shown in FIG. 16 as 72 is lifted until it touches the foot plate 73 having foot plate joint 74 attached to a fulcrum arm 75. The up limit microswitch 70 is actuated by engagement with the fulcrum arm 75 which also causes the stack travel direction to be reversed and causes the stack 72 to be moved in the downward direction. The downward movement is arrested when microswitch 71 is engaged by fulcrum arm 75 activated by the weight of the freely suspended foot plate 73. The stack is driven, as previously explained by pinions 43 and motor 46 with the pinions being attached to the motor on shaft 76. The housing which carries the rack guides 44 as well as the motor 46 is identified as 77 in FIG. 16.

At the time when the up limit microswitch 70 is activated an appropriately activated solenoid valve 89a (as further explained herein) directs a side air blast through a side air blast tube 89b affixed to the air nozzle holding frame 86. The side air blast tube is activated by a side air blast cam 90 and side air blast cam switch 91 affixed to the rotating portion of the shaft 50 (but not shown). The duration of side air blast can be adjusted by appropriate electrical control means. The pocket blank B is prevented from being blown away or blown sideways because foot plate 73 is still resting on the stack of plies. However, the air blast does help in partially separating the individual ply which has been picked up by the tape 49. As previously mentioned, as soon as the up limit microswitch 70 is actuated by the fulcrum arm 75, the stack 72 continues

downwardly and the down limit microswitch 71 becomes activated. The down limit microswitch 71 also is keyed in the electrical means and it deactivates the side air blast solenoid valve 89b. However, the stack may continue to move downwardly until it comes to a stop which may be determined by the length of time during which the pickup motor 46 is engaged.

A single ply B is now attached to the tape pickup at point 58 and thus the tape 49 carries the pocket blank around the shroud 60 upwardly. A stagewise pickup sequence is illustrated in FIGS. 15 to 15c. Although generally a single ply may be attached to the tape 49, it is possible that two plies may still adhere to each other and be picked up by the tape 49. A short air pulse called "a delayed air blast" is employed in order to insure that no additional plies may be picked up. This air blast is effected through a nozzle 68 (when a solenoid valve 68a is actuated) and it is directed along the length of the ply, thus separating two plies should the same be stuck together. A separated ply then settles down on the stack 72 to be ready for pickup again.

The delayed air blast may be keyed into the side blast nozzle cam switch 91 with appropriate delay elements; nozzle 68 on the housing frame 86 and the height and the location thereof may be adjusted on appropriately provided slots 86a on the end member 86b of the frame 86.

Additionally, an "up air blast" air blast tube 67 which may consist of a plurality of tubes or an individual nozzle placed on end member 86b on frame 86 may be provided for reducing the wrinkling of the pocket blank ply as it is being pulled over the sheet metal shroud 60 to guide the pocket blank around shroud 60. The "up air blast" is continued simultaneously while the pocket transfer device rotates for about 90° from the pickup position. The purpose of the "up air blast" is to form a drooping front edge of the single ply by urging the ply against the sheet metal guide 60. This air-assisted conforming prevents the aforementioned wrinkling of ply B. As the tape 49, at the tape guide head 58, carries the pocket blank ply 180° from the pickup position, a stripper plate 69, which has a notched out portion 69a through which the tape head guide roller 58 passes, strips the ply and a puller wheel 61 engages the ply. Puller wheel 61 may also be activated by a double-acting pneumatic cylinder 95 via solenoid valve 62 or activated on upstroke and deactivated by spring 64, thus, engaging the ply and sending it over the table 65 onto the rollers 66.

The puller wheel 61 stays in the down position until enough of the ply has been advanced onto the conveyor rollers 66 such that the friction of the conveyor rollers 66 will be sufficient to transport the ply without an assist from the puller wheel 61.

A side guide plate 66a is placed over the rollers askewly to the direction perpendicular to the axis of rotation of rollers 66 so as to cause the rollers 66 to urge and guide the ply along guide 66a and onto the sewing table 134.

The pocket blank pickup device 47 will continue to rotate in clockwise manner until it reaches the bottom of the stack 72 which marks the beginning of a new cycle. A side guide 87 for table 41 is also provided which may appropriately constrain the stack of cloth as it moves up and down with the table 41.

The roller conveyors 66 are housed in a housing 93; and these rollers 66 may be appropriately driven by chains or intergeared and driven by a motor from a power takeoff gear conventionally known in the art. Motor 46 which drives table 41 pocket and transfer motor 48 driving pocket transfer device 47 is a motor which exhibits instant stopping characteristics. These motors are freely available in the trade.

In reference to FIG. 14 or 19a manual tape feed device is provided for manually winding tape 49 onto tape takeup reel 56b. A latch rod holder 96 is provided for engaging a plunger latch wheel 96a at the end of crank 97 in such a manner as to prevent the fixed shaft 51 from rotating. When the tape 49 is fed manually such as when installing a new reel of tape and when feeding the same around the head roller 58 and onto the

takeup reel 56b, the small plunger latch wheel 96a is pulled out of the latch rod holder 96 against spring 96b and the crank 97 is rotated by hand. Shaft 51 which is fixedly held by the crank 97 is then rotated which drives worm 53 and the worm gear 54 without rotating the housing 59, (whereas normally, the worm gear 54 is driven around the worm 53). A control panel which houses the electrical and pneumatic control devices associated with the single ply pickup and transfer device is identified by 94.

10 b. Electrical Control Means

The electrical control means as represented by the electrical circuit for the single ply pocket blank pickup and transfer device 40 is illustrated at 800 in FIG. 20. The mechanical means and the operating cycle of this device was described above. The manner in which control circuit 800 operates will now be explained by describing what happens at each step in its operating cycle.

20 INITIAL CONDITIONS PRIOR TO START OF OPERATING CYCLE

Standard alternating current is applied to AC power terminal 803 and ground terminal 802. Twenty-six volts DC is applied between DC power terminal 801 and ground terminal 802. The following conditions exist:

1. The stack holder table 41 is in a down position, causing down limit switch 71, and up limit switch 70, to assume their respective positions.
2. Relays 804, 805, 806, 807, 808, and 809 are deenergized.
3. Diodes 820 and 830, of first delay circuit 810 and second delay circuit 811, respectively, are grounded through relay 806. This places both delay circuits in hold mode as follows:
  - a. Capacitors 821 and 831 are bypassed to ground through diodes 820 and 830, respectively.
  - b. Zener diodes 825 and 835 are thus nonconductive.
  - c. Transistors 827 and 837 are biased into nonconduction by resistors 826 and 836, respectively.

START OF OPERATING CYCLE

The operating cycle is initiated by completing the ground-path to start terminal 812. This is accomplished through output terminal 904 of electrical control circuit 900, in a manner to be described hereinafter.

This provides a groundpath for the coil of relay 804, causing it to energize and latch through the up limit microswitch 70. The following then occurs:

1. The "up" winding of pickup motor 46 is energized through relay 804, causing the stack holder table 41 to travel up. As the stack 72 rises, down limit switch is mechanically actuated, causing it to assume its respective position.
2. Transistor 844, which is normally biased into nonconduction by diode 843, is caused to conduct momentarily by a drive pulse through the pulse network composed of resistor 840, capacitor 841 and resistor 842. This momentarily energizes relay 805, which is the emitter path of transistor 844.
3. Pocket transfer motor 48 is momentarily energized through relay 805. The momentary rotation of pocket transfer motor 48 mechanically actuates stop cam switch 81, causing it to close, thereby energizing pocket transfer motor 48.
4. After one-half revolution of pocket transfer motor 48, puller cam switch 83 is momentarily mechanically actuated causing it to momentarily close. Puller solenoid valve 62a is thereby momentarily energized, causing the pocket ply to be transferred away.
5. After one revolution of pocket transfer motor 48, stop cam switch 81 is mechanically actuated causing it to open, thereby deenergizing pocket transfer motor 48.

STACK CONTACTS TAPE

When the stack contacts the tape, up limit switch 70 is mechanically actuated, causing it to assume its up position, with the following results:

1. Relay 804 is deenergized, thereby deenergizing the "up" winding of pickup motor 46. 5
2. Relay 806 energized through the up limit switch 70, and latches through relay 809, with the following results:
  - a. The "down" winding of pickup motor 46 is energized through relay 806, causing the stack to travel down. 10
  - b. Transistor 853, normally biased into nonconduction by resistor 852, is driven into conduction through resistors 850 and 851, and relay 806.
  - c. Side air blast solenoid valve 89a, in the collector path of transistor 853, is energized. 15
  - d. Diodes 820 and 830, of first delay circuit 810 and second delay circuit 811, respectively, are ungrounded. Both delay circuits remain in hold conditions, pending actuation of down limit switch 71, which will provide DC voltage to the delay circuits. 20

STACK'S DOWNWARD TRAVEL ACTUATES DOWN LIMIT SWITCH

As the stack travels down, the down limit switch 71 is mechanically actuated, causing it to assume its respective position, with the following results:

1. Side air blast solenoid valve 89a is deenergized. Diode 819 prevents transistor 853 from being damaged by the back e.m.f. generated when side air blast solenoid valve 89a is deenergized. 30
2. Twenty-six volts DC is applied to resistors 824 and 834, of first delay circuit 810 and second delay circuit 811, respectively. This causes both delay circuits to be energized as follows:
  - a. Resistor 824, variable resistor 823, capacitor 821 and resistor 822 form a first series RC circuit. Resistor 834, variable resistor 833, capacitor 831 and resistor 832 form a second series RC circuit. Twenty-six volts DC is applied to both series RC circuits through down limit switch 71. 40
  - b. Capacitors 821 and 831 charge at rates which are adjustable by variable resistors 823 and 833, respectively. Component valves are selected so that the time constant of the first series RC circuit is shorter than the time constant of the second RC circuit, thereby causing capacitor 821 to charge faster than capacitor 831. 45

END OF FIRST DELAY INTERVAL

After a period of time, corresponding to that required for capacitor 821 to charge until the voltage at the junction of capacitor 821 and zener diode 825 equals the zener voltage of zener diode 825, first delay circuit 810 switches as follows:

1. Zener diode 825 conducts, providing base drive to transistor 827. 55
2. Transistor 827 assumes a conducting state causing relay 807, in its collector path, to energize with the following results:
  - a. Capacitor 815, which was previously charged through resistor 816, is connected to the coil of relay 808. This momentarily energizes relay 808. 60
  - b. Delayed air blast solenoid valve 68a is momentarily energized through relay 808, producing the delayed air blast referred to hereinbefore. Capacitor 813 and resistor 814 form an arc-suppressing circuit to protect the contacts of relay 808.

END OF SECOND TIMING INTERVAL

After a period of time, corresponding to the time required for capacitor 831 to charge until the voltage at the junction of capacitor 831 and zener diode 835 equals the zener voltage of zener diode 835, second delay circuit 811 switches as follows:

1. Zener diode 835 conducts, providing base drive to transistor 837.
2. Transistor 837 assumes a conducting state causing relay 809, in its collector path, to energize.
3. The ground path to the coil of relay 806 through relay 809 is opened, causing relay 806 to deenergize.
4. Diodes 820 and 830, of first delay circuit 810 and second delay circuit 811, respectively, are grounded. This causes both delay circuits to reset as follows:
  - a. Capacitors 821 and 831 discharge through diodes 820 and 830, respectively.
  - b. Zener diodes 825 and 835 thus return to their nonconducting states.
  - c. Having no base drive, transistors 827 and 837 return to their nonconducting states, causing relays 807 and 809 to deenergize. Diodes 817 and 818 prevent transistors 827 and 837, respectively, from being damaged by the back e.m.f. generated when relays 807 and 809 deenergize.

All circuits have thus returned to their initial conditions, marking the completion of one operating cycle of the pocket blank pickup and transfer.

25 THE FACING PATCH AND THE POCKET-BLANK-MATING DEVICE 100

As the facing patch B is placed on the pocket blank A by device 100, which blank A is on the sewing machine 131 table 134 holding in ready sewing position the pocket blank, the discussion about this step will anticipate somewhat the description about the sewing machine 131 operation and construction which will be covered below in greater detail. Moreover, the electrical control means which are used in conjunction with the mating device 100 will be discussed after the mechanical means associated with the sewing machine operation will be covered.

Thus, after the single ply pocket blank A travels down the conveyor rollers 66, it is guided onto the sewing machine table 134 against the end and edge guide 152 and underneath the guide apron or guide hood or catch hood 148. Also, as the sewing machine presser foot 135 is raised and as the needle 133 of sewing machine 131 is in the up position, the pocket blank readily slides over the table 134 and is guided into its position by the conveyor rollers 66 which still engage the tail end of the pocket blank and urge it against the sewing machine end and edge guide 152. At this time the facing patch is traveling along the rollers 19 which have closely conforming guide edges 19c spaced apart slightly more than the width of the facing patch B. The patch is conveyed onto the facing patch mating unit 100 depicted in FIG. 21.

40 FACING-PATCH-MATING DEVICE 100

55 This device consists of an airdrop tray 101, which has at its end an adjustable stop 102 with a guide rod 121 inserted spatially above the surface. The travel of the facing patch is aided by means of slanted airholes 103 urging the facing patch against the stop 102 by means of low-velocity air flowing through these slanted holes 103.

60 The air tray in its up position is shown in FIG. 21 and in its dropped position by dashed lines in FIG. 22. Arrival of the facing patch along rollers 19 is detected by photocell 104 in cooperation with the facing detection photocell lamp 105. 65 The air tray 101 has a side guide 106 which insures the proper positioning of the facing patch under the vacuum bar 114. The cooperation between the pocket and the facing patch is also insured through the pocket side guide photocell 122 which activates a pneumatic cylinder movable guide 124 (not shown) 70 after the photocell 123 signals a noninterrupted beam and; hence, the improper position of the pocket. At a later point herein, this operation will be explained in conjunction with the electrical control means used with this unit.

75 After the airdrop tray 101 has received the facing patch, the facing is urged against the stop 102 by airholes 103, and at this

position the facing is engaged by the vacuum bar 114 which is situated to allow the proper placement of the facing patch under the presser foot 134 and the presser foot needle slot 141. As a general rule, the vacuum bar will be engaging the facing at a distance of approximately three-eighths of an inch away from the side guide 106. After the vacuum has been applied to the vacuum bar 114 through appropriate holes, from a source of vacuum through flexible hoses 115, the air tray 101 pivots downwardly hinged on shaft 107, to its drop position as shown in FIG. 22 which is achieved by means of the air tray drop cylinder 108 which is accomplished by the cylinders 108 pulling upwardly against the spring 110, through the lever 109, the air tray 101.

As the vacuum bar 114 has engaged the facing patch B and holds it in place suspended above the pocket blank A a pneumatically activated cylinder 116 having a cylinder rod 117 extends the vacuum bar 114 along the vacuum bar slide guide 119 forwardly and downwardly onto the sewing table 134 until the forward and downward motion is stopped by the appropriately angled slide guide 119 having a forward microswitch 118 mounted thereon.

As the microswitch 118 is tripped, it cuts off the vacuum flowing through hoses 115 by means of a valve (not shown). Operation of this sequence from the electrical standpoint will be further explained herein.

As the air tray 101 is fixed and attached to the frame 111 held above the conveyor rollers 66 and as the conveyor rollers 19 are placed spatially above the conveyor roller 66, the appropriate retraction of cylinder 108 is controlled by the air-drop tray microswitch 113. This retraction timing and speed is adjusted so that when the forward stroke of cylinder rod 117 is completed, the facing patch readily clears the side guide 106 of air tray 101.

The end stop 102 is provided with a threaded adjustment bolt 102a for placing the facing accurately on the pocket blank.

The forwardly and slantedly stroking cylinder 116 is attached to frame 111 by means of a cylinder holding frame 120 for aligning the cylinder 116 and its rod 117 for proper guidance of the vacuum bar 114.

THE SEWING MACHINE UNIT 130

As previously mentioned, the sewing unit 130 sews the facing patch onto the back pocket blank. The sewing device or unit 130 is illustrated in FIGS. 22 to 24. This sewing device consists of a sewing machine 131 having its head 132 facing towards the conveyor rollers 66 from which the pocket blank A travels onto a movable table 134 on which the back pocket blank A is placed under the presser foot 135. The head 132 of the sewing machine 131 houses the sewing machine needle 133 and the needle bar 133a. As the worktable 134 is moved by means of a rack 153 in a manner further explained herein, no feed dogs are necessary for moving the workpiece. Thus, the pocket blank A which rests on the movable table 134 having been placed on its proper position by the conveyor rollers 66 and side guide 124 (not shown) which has urged the pocket blank against a side ledge 150 of the work table 134, and placed the pocket blank under the receiving or capture hood 148, which has an up-turned receiving ledge 148b to prevent the pocket blank from climbing over the end and side ledge 150. An opening 148a is provided in the capture hood 148 which is necessary for transmitting a signal from the photocell 145 cooperating with the photocell lamp 146 to signal the proper position of the pocket blank as it is urged against the end stop 142 provided with capture hood 148. For adjusting and securing the capture hood 148, a capture-hood-holding frame 149 is attached to the side ledge 150. The presser foot 135 may also be called a "clamp foot."

As the worktable at the beginning of the cycle is in its rightmost position with the presser foot raised 135 and the needle 133 and needle bar 133a in the up position, the presser foot cylinders 137 have retracted the presser foot guide rod

138 upwardly, guided by the upwardly moving guide rails 140 which hold the guide rail 138 and its presser foot lugs 138a. Presser foot rail 138 is guided in a horizontal plane by rollers 139, mounted on the vertical guide rail 140.

5 The presser foot cylinders 137 are fixedly attached to the cylinder holding frame 144 which in turn is attached to the sewing machine 131. The vertical as well as the horizontal guide rail 140 and 138, respectively, are engaged by the sewing machine presser-foot-holding frame 136 which moves with the movable table 134 and which frame extends as an elbow over this table. A slot 141 in the presser foot 135 is provided for obtaining the straight seam on the facing patch.

As it is evident from the drawings, the movable table 134 in 15 cooperation with the presser foot 135 walks the work from right to left over the stationary table 143. At the completion of the sewing cycle the rightmost position of the table is signaled by microswitch 147, attached to the housing of the sewing machine 131 and tripped by the presser foot frame 136.

10 As side guide ledge 150 moves with the table 134, it is attached to spacer frame 152 attached to the moving rack 153 by bolts 152 but also fixedly holding end and side guide ledge 150 by means of spacer 152. The straddle frame 151 guides the rack 153 and is permanently affixed to a stationary part of 25 the sewing machine. In turn, the whole assembly is joined together, i.e. table 134, ledge 150, hood 148, hood holding frame 149, presser foot frame 136, and spacer 152.

20 The return cylinder rod 154 which is anchored to the rack 153 at anchor point 169 (the cylinder 155 being permanently 30 attached to cylinder holding rack 155a) places in receiving, rightmost position, when it is extended by the cylinder 155, the sewing table 134.

25 After the rack 153 has reached its rightmost or leftmost 35 positions, it is stopped by the rack stops 168 abutting the straddle frame 151 and spacer 152. Appropriate adjustments may be made by the rack stops 168 as needed.

30 In order to drive leftwardly the rack 153, power is taken from the sewing machine 131. A sewing machine such as 40 Singer 269 disclosed in U.S. Pat. No. 2,938,477 is used for the sewing operation. This is a lock stitch type of machine and designed to sew a fixed number of stitches after which it automatically stops and trims the top and bottom threads by known means (not shown) thus, freeing a workpiece from the 45 machine. This machine has an appropriately sized base gear 167 which makes one complete revolution. Hence, the linear traverse of the sewing machine table 134 can be selected for each sewing cycle to assure a fixed sew length.

50 Base gear 167 is connected to intermediate transfer gears 166, joined through a shaft 166a which drives gear 161 which in turn is coupled to clutch and gear plate 160. By proper 55 selection of these gears, the correct stitch length can also be selected. The pinion 156 which is engaged with rack 153 is in turn coupled to an electric clutch 158. Commercially available electric clutches are used and these are readily obtainable.

55 The electric clutch 158 in the base of the sewing machine is for the purpose of disengaging the sewing table 134 after the completion of the stitch line so that cylinder 155 can return the table 134 to its rightmost position.

60 The clutch 158, which is a magnetically engageable clutch, couples with clutch and gear plate 160 during the sewing cycle. This clutch and gear plate 160 consists of an interiorly cut gear sliding on a slideable sleeve gear 162. This slideable sleeve gear is fixedly attached to the shaft 163. The slideable sleeve gear 162 in turn is fixedly engaged to and attached to gear 161. When the power is removed from clutch 158, the clutch and gear plate 160 drops or slides vertically on the sleeve gear 162 and gear 161 transmits no power to the clutch and thus to 65 the pinion 156. However, when the baseplate 160 is engaged by clutch 158, gear 162 is driven from the sewing machine base gear 167 through the intermediate gears 166. The sewing machine 131 is also modified to replace the sewing machine clutch pedal (not shown; normally foot operated) with an air cylinder (not shown).

RAKE DEVICE 180

After the moving table 134 has reached its leftmost position, the pocket with a facing patch sewn thereon must be removed from the sewing machine 131. This is effected by means of a device designated as "rake" and it is shown in FIG. 26 as 180. Rake 180 removes the pocket blank by straddling the leftmost portion of the presser foot 134 at its leftmost position with puller feet 182 in form of two wheels attached at terminal ends to lengthwise extending axis 182a mounted on a chain 181. The wheels 182 are about 3 inches apart on the axis 182a. The axis 182a is attached to the rake chain 181 which pulls or rakes the workpiece or pocket blank from table 134 onto table 183 which abuts the stationary sewing machine table 143. The chain 181 is driven by the chain drive motor 187 through a chain 188 driving a driven sprocket chain gear 188a attached to an axis 188b to a chain sprocket gear 185. Table 183 is highly polished metal plate. An adjustable sprocket wheel 186 is provided as an idle wheel and also as an adjustable chain takeup wheel. A freely rotating sprocket wheel 184 defines the length of the rake sweep and it is mounted on the rake frame 189 which houses the motor 187, the idle wheel 186, as well as the stop microswitch 192 which is used for stopping motor 187 and placing the rake wheels 182 in position when the stop cam 191 mounted on the outside of the chain 181 to clear the sprocket wheels 184, 185 and 186 arrives at an appropriately adjusted switch 192 trip position. The rake frame 189 is mounted by an appropriate elbow-shaped bracket 190 to extend over the table 183 and thus to allow the sweeping of the pocket underneath it onto the next roller conveyor 229 shown in FIG. 28.

ELECTRICAL CONTROL MEANS FOR THE FACING PATCH MATING 100, SEWING 120 AND RAKE DEVICES 180

The electrical control means are illustrated by the electrical control circuit for the mating, sewing and transfer devices and is indicated as 900 in FIG. 27. The operating cycles of these devices were discussed above. The operation of electrical control circuit 900 will now be explained by describing what happens at each step in its operating cycle.

INITIAL CONDITIONS PRIOR TO START OF OPERATING CYCLE

Standard alternating current is applied to AC power terminal 901 and ground terminal 902. One hundred fifty volts DC is applied between DC terminal 903 and ground terminal 902. The following conditions exist:

1. Relays 910, 911, 912, 913, 914, 915, 916 and 917 are deenergized.
2. Table 134 return solenoid valve 1553 is energized through presser foot microswitch 135a (not shown, located on presser foot lift bar linkage, the lift bar can be removed and is replaced by cylinders 137) causing the table 134 to assume its retracted position.
3. Table retract microswitch 147 is mechanically held closed by the retracted table 134.
4. Airdrop tray 101 solenoid valve 103a is energized through relay 914. This causes air to be blown through the slanted airholes 103.
5. Presser foot solenoid valves 137b are energized, through sewing machine clutch microswitch 131a and facing forward microswitch 118 causing the presser foot 135 to assume its up position.
6. Vacuum solenoid valve 115a, electric clutch 158, sewing machine clutch 131d, drop tray 101 actuating cylinder 108 solenoid valve 108a, facing forward cylinder solenoid valve 116a, and rake motor 187 are deenergized.

START OF OPERATING CYCLE

The operating cycle is initiated by the coexistence of the following three conditions:

1. Table 134 is in its retracted position.
2. Pocket A is present and correctly aligned.
3. Facing is present and correctly aligned.

If correctly aligned, the pocket and facing will interrupt the paths of the light beams from lamps 123, 145 and 105 to pocket side photocell 122, pocket front photocell 146, and facing photocell 104, respectively. Pocket side photocell is connected to a first photocell amplifier 920. Pocket front photocell 146 is connected to a second photocell amplifier 921. Facing photocell 104 is connected to a third photocell amplifier 922. The result is that the covering of pocket side photocell 122, pocket front photocell 146 and facing photocell 104 creates output signals at output terminals 923, 924 and 925 of first photocell amplifier 920, second photocell amplifier 921 and third photocell amplifier 922, respectively, with the following results:

2. Relay 912 is energized by the output signal at output terminal 923 of first photocell amplifier 920.
2. Relay 911 is energized by the output signal at output terminal 924 of second photocell amplifier 921.
3. Relay 910 is energized by the output signal at output terminal 925 of third photocell amplifier 922.
4. Relay 913 is energized through table 134 retract microswitch 147 and relays 910, 911, 912 and 915, with the following results:
  - a. Vacuum valve 115a is energized through relay 913 and presser foot microswitch 135a. This causes the facing to become attached to vacuum bar 114.
  - b. Input terminal 932 of first delay circuit 930 is grounded through relay 913.

END OF FIRST DELAY TIME INTERVAL

After a period corresponding to the delay time of first delay circuit 930, output terminal 933 of first delay circuit 930 will assume a ground potential, causing relay 914 to be energized, with the following results:

1. Air drop tray solenoid valve 103a is deenergized, causing the airflow through the slanted airholes 103 to be terminated.
2. Drop tray 101 solenoid valve 108a is energized through relay 914, causing drop tray 101 to pivot down.
3. Machine delay circuit 926 is energized through relay 914. After an appropriate time delay, relay 918 will be energized, causing output terminal 904 to be grounded. This starts twist separation device 39 and pocket pickup and transfer device 40 as described herein before.

DROP TRAY ASSUMES DOWN POSITION

When drop tray 101 reaches its down position, the following occurs:

1. Drop tray microswitch 113 is mechanically actuated causing it to close.
2. Facing forward solenoid valve 116a is energized through drop tray microswitch 113 and sewing machine clutch microswitch 131a, causing vacuum bar 114 to travel forwardly and downwardly.

VACUUM BAR ASSUMES DOWN POSITION

When vacuum bar 114 reaches its down position, the following occurs:

1. Facing forward microswitch 118 is mechanically actuated causing it to open.
2. Presser foot solenoid valve 137b, which was initially energized through facing forward microswitch 118 and sewing machine clutch microswitch 131a, is deenergized. This causes presser foot 135 to travel downwardly.

PRESSER FOOT ASSUMES DOWN POSITION

When presser foot 135 reaches its down position, trapping the facing B against the pocket blank A, presser foot microswitch 135a is mechanically actuated, causing it to assume its down position, with the following results:

1. Vacuum valve 115a is deenergized causing the facing to be released from vacuum bar 114.
2. Table return solenoid valve 155e is deenergized.
3. Electric clutch 158 is energized through presser foot microswitch 135a, causing sewing machine base gear 167 to be coupled to sewing machine table 135 as previously explained under the mechanical means.
4. Sewing machine clutch (not shown) is energized through presser foot microswitch 135a and relay 913. This starts the sewing machine, which will run for one sewing cycle, after which it automatically stops.
5. Sewing machine clutch microswitch 131a is mechanically actuated by sewing machine clutch (not shown) causing it to assume its engaged piston, with the following results:
  - a. Facing forward solenoid valve 116a is deenergized, causing the vacuum bar to return to its initial position.
  - b. Relay 916 is energized through sewing machine clutch microswitch 131a. This connects capacitor 936 to +150 v. DC causing it to charge to that voltage.
  - c. Input terminal 934, of second delay circuit 931, is grounded through sewing machine clutch microswitch 131a.

END OF SECOND DELAY TIME INTERVAL

After a period corresponding to the delay time of second delay circuit 931, output terminal 935 of second delay circuit 931 will assume a ground potential, causing relay 915 to be energized, with the following results:

1. Relay 913 is deenergized.
2. Relay 914 is deenergized.
3. Drop tray solenoid valve 103a is energized through relay 914.
4. Drop tray solenoid valve 108a is deenergized causing the drop (air) tray 101 to return to its initial position (by down stroke of cylinder 108).

END OF SEWING CYCLE

After one sewing cycle, sewing machine clutch automatically disengages. This mechanically actuates sewing machine clutch microswitch 131a, causing it to return to its disengaged position, with the following results:

1. Relay 916 is deenergized, connecting capacitor 936, which has previously been charged to +150 v. DC through resistor 937 and relay 917. This momentarily energizes relay 917 with the following results:
  - a. Rake motor 187 is momentarily energized through relay 917.
  - b. The momentary rotation of rake motor mechanically actuates rake stop microswitch 192, causing it to close. Rake motor 187 is energized through rake stop microswitch 192, causing the sewn pocket to be transferred away by rake wheels 182.
  - c. After one revolution of rake motor 187, rake stop switch 192 is mechanically actuated causing it to open, thereby deenergizing rake motor 187.
2. Light beams from lamps 123, 145 and 105 now illuminate pocket side photocell 122, pocket front photocell 146 and facing photocell 104, respectively. This causes relays 912, 911 and 910 to be deenergized by photocell amplifiers 920, 921 and 922, respectively.
3. Presser foot solenoid valve 137a is energized through sewing machine clutch microswitch 131a and facing forward microswitch 118. This causes the presser foot to lift, which mechanically actuates presser foot microswitch 135a, causing it to assume its up position with the following results:
  - a. Electric clutch 158 is deenergized.
  - b. Vacuum valve 115a is energized through presser foot microswitch 135a and relay 913.
  - c. Table return solenoid valve 155e is energized through presser foot microswitch 135a causing the carriage to retract.

All circuits have thus returned to their initial conditions, making the end of one operating cycle. The mating, sewing and transfer devices are thus mechanically and electrically reset.

FACING FOLDER DEVICE — 200

a. Mechanical Means

As next step in the sequence, in order to hide the stitch seam formed in the sewing unit 130, the facing folder is folded in a facing-folding device designated as 200. This device is illustrated in FIG. 28. The conveyor rollers are designated as 229 and the rake device 180 has placed the pocket blank A on these. The rollers 229 are driven in the same manner as conveyor rollers 66, i.e. by means of a motor (not shown) or inter-linked to conveyor rollers 66. These rollers rotate in a clockwise manner. The pocket blank is conveyed by urging the same against a guide rail 229b which is oriented askewingly across the conveyor rollers 229 and thus allow the rollers to urge the pocket blank in a predetermined manner towards the facing folder.

When the pocket blank covers the folding device photocell 218 interrupting the path from photocell lamp 217, the forward pocket blank cylinder 201 and back clamp cylinder 202 having a clamp foot 201a and 202a are simultaneously activated arresting the forward motion of the pocket blank. The back pocket blank clamp cylinder foot 202a engages the blank between the engaging surface 203, and forward clamp foot 201a engages the blank between engaging surface 231.

30 An air blast tube 204 is provided to lift the facing from the pocket blank. By means of a heated platen 205, which is urged forwardly by pneumatically operated cylinder 207 pushed by a cylinder rod 208 and guided by pivoting guide rails 206, the facing is pressed as aided by an air-operated press cylinder 210. At the end of the press cylinder rod 210a is attached a ram head 211 which engages the heated platen 205 which platen is pivoted downwardly as guided by guide bolts 212. After holding the folded facing patch for appropriately adjusted time depending on the material, the heated platen 205 is removed from it by retracting the ram head 211. The side rails 206 are urged upwardly by the extended springs 213. The facing in its pressed position is shown in FIG. 29.

The heated platen 205 has two of the side guide rails 206 and on inside thereof these carry roller guides 209 on roller guide frame 209a. These rails are pivoted at the guide rail pivot bracket 216 placed on top of guide rail frame 215 attached to the sides of the conveyor 229.

50 The length of the cylinder rod 208 can be internally adjusted in the cylinder 207. A stop 214 may also be provided which arrests the forward motion of the heated platen 205. After the press clamp cylinder 210 has been retracted and the platen 205 urged upwardly, the forward and rear clamp cylinders 201 and 202 are released. These are internally spring loaded and retract when the pneumatic pressure is removed. A rotating puller 219 wheel is appropriately timed and engaged with the pocket blank as further explained in the discussion pertaining to the electrical means. Thus, cylinder 223 on a downstroke swings pivoting frame 222, and the puller wheel 219 into an engagement with the pocket blank for accelerating and forward the same to the side-edge-folding device 250. Accelerating a pocket blank to the conveyor speed is desirable for transfer of this blank onto the feed conveyor 251 shown in FIG. 31.

60 The puller wheel cylinder 223 rod 224 presses down through the articulated linkage 225 the puller wheel frame 222 which contains bushings 220a and 220b (not shown) which rotate shaft 220 by means of a belt 221 taking the power from one of the conveyors 229, as previously explained in conjunction with the single ply pickup and transfer device 40.

75 It has been found that the necessary acceleration can be obtained by the size of the puller wheel, the length of time the puller wheel is engaged with the pocket blank, and the ap-

proper size of the pulleys 221a and 221b, (not shown) which are mounted on shaft 220 and a conveyor roller 229, respectively. The puller wheel frame 222 is retracted by the puller-wheel-holding frame spring 226. The heated and movable platen 205 may also be aided in pressing of the facing patch by the bottom platen 227 which may optionally be heated.

A frame 232, shown in FIG. 28, attached to sides of conveyor 229a is provided for mounting the cylinder 210, forward clamp cylinder 201, forward stop 214, photocell lamp 219, guide bolts 212, and puller wheel pneumatic cylinder 223.

The folded and pressed facing hides the stitching and this blank is now sent onto the feed-in conveyor 251 of the side edge folder 250.

b. Electrical Control Means

The electrical control means as illustrated by the electrical circuit for the facing folder device 200 is indicated as 1000 in FIG. 30. The operating cycle of this unit was discussed above. The operation of the control circuit 1000 will now be explained by describing what happens at each step in its operating cycle.

INITIAL CONDITIONS PRIOR TO START OF OPERATING CYCLE

Standard alternating current is applied to AC power terminal 1001 and ground terminal 1002. One hundred fifty volts DC is applied to DC terminal 1003 and ground terminal 1002. Relays 1010, 1011, 1012, 1013, 1014 and 1015 are deenergized.

START OF OPERATING CYCLE

The operating cycle is initiated by the presence of a pocket in the facing folder device 200. If correctly aligned, the pocket will interrupt the path of the light beam from lamp 217 to facing folder photocell 218. Facing folder photocell 218 is connected to photocell amplifier 1020. As a result of the covering of facing folder photocell 218, an output signal at output terminal 1021 of facing photocell amplifier 1020, is created with the following results:

1. Relay 1010 is energized by the output signal at output terminal 1021 of photocell amplifier 1020.
2. Capacitor 1016, which was previously charged to 150 volts through relay 1010 and resistor 1018, is connected to relay 1011, causing relay 1011 to be momentarily energized.
3. Relay 1012 is momentarily energized through relay 1011, and latches through relay 1014, with the following results:
  - a. Forward and rear clamp solenoid valves 201d and 202d, (only one is shown in FIG. 30 as both cylinders 201 and 202 can be operated from one valve) respectively, are energized through relay 1012, causing the pocket to be clamped in place.
  - b. Air blast solenoid valve 104a is energized through relays 1013 and 1012.
  - c. Facing folder forward solenoid valve 207a is energized through relay 1012, causing the press head to travel forward.
  - d. First delay circuit 1022 is energized through relay 1012.

END OF FIRST DELAY INTERVAL

After the period required for the press head to reach its forward position, corresponding to the delay time of first delay circuit 1022, relay 1013 is energized by first delay circuit 1022, with the following results:

1. Air blast solenoid valve 204a is deenergized.
2. Press valve 210d is energized through relays 1013, 1012 and 1014, causing the ram foot 211 to press against the press head 205.
3. Second delay circuit 1023 is energized through relay 1013.

END OF SECOND DELAY INTERVAL

After an appropriate pressing of the facing patch B, corresponding to the delay time of second delay circuit 1023, relay 1014 is energized by second delay circuit 1023, with the following results:

1. Capacitor 1017, which was previously charged to 150 volts through resistor 1019 and relay 1014 is momentarily connected to relay 1015, causing relay 1015 to be momentarily energized.
2. Puller valve 223d is momentarily energized through relay 1015, causing the pocket to be pulled out of the facing folder. The light beam from lamp 217 now illuminates facing folder photocell 218, causing relay 1010 to be deenergized by photocell amplifier 1020.
3. Relay 1012 is deenergized, with the following results:
  - a. Press valve 210d is deenergized, causing ram foot 211 to return to its initial position.
  - b. Forward and rear clamp solenoid valves 201d and 202d, respectively, are deenergized, causing the pocket to be released.
  - c. Facing folder forward solenoid valve 207a (a four-way valve) is deenergized, causing the press head 205 to return to its initial position.
  - d. First delay circuit 1022 is deenergized, causing relay 1013 to deenergize.
  - e. Second delay circuit 1023 is deenergized, causing relay 1014 to deenergize. Relay 1014 is thus only energized for a short time interval. This time interval exceeds the time required for relay 1015 to be energized by capacitor 1017, thus permitting relay 1015 to be momentarily energized in the manner hereinbefore described.

All circuits have thus returned to their initial conditions marking the completion of one operating cycle. The facing folder unit 200 is thus mechanically and electrically reset.

POCKET BLANK SIDE EDGE FOLDING & PRESSING DEVICE

a. Mechanical Means

From the patch facing folder device 200, the pocket blank is then sent to the side folder and pressing device 250 illustrated in FIGS. 31 to 36. This device consists of the following major units: Feed conveyor 251 previously mentioned, an inner die unit 258a illustrated in FIGS. 32 and 34; a left-hand and a right-hand edge-folding unit 280a and b which are substantially the same in their mechanical operation and are illustrated in FIGS. 33, 33a, 33b and 34; and a front arrest gate and puller unit 298 illustrated in FIG. 32a.

In this device a longitudinal fold is made and pressed along the edges of the pocket blank, i.e. along both longitudinal sides thereof, to form about a one-half inch wide folded edge so that when the pocket blank is subsequently folded upon itself, it may be sewn into a pouch, with seams which are sufficiently strong to hold the contents normally placed in pockets.

The subunits of the side folder and pressing device 250 mentioned will be explained in reference to FIG. 31, showing their location in the top view of the edge folding and pressing device 250a.

For easy envisioning of the actual edge seam folding and pressing sequence, reference is made to FIGS. 35a to 35h illustrating the operation cycle.

- 65 Returning to FIG. 31, an incoming pocket blank enters the edge folding and pressing device 250 guided by a side guide rail 251a in the form of an angle, and mounted over conveyor rollers 229. The side die unit 258 is mounted over the conveyor section and supported over the same by four legs 294.
- 70 The pocket blank is advanced by means of the conveyor rollers 251 and moved along until the blank reaches the folder conveyor rollers 252. The rollers 252 in this section are shorter than those in section 251 and are between the heated platens 296. As the pocket blank reaches the leading edge stop apron 298a shown in FIG. 32a, and upon activation of the

leading edge photocell 254 (not shown) when covering the path from lamp 255 shown in FIG. 31, a leading edge gate 253 is brought down to stop the forward motion of the pocket blank by a pneumatically operated cylinder 253a driving down gate 253. The cylinder 253a is affixed to frame 253b which by crossmember 253c is conveniently attached to legs 294 or leg braces 294a. In reference to FIG. 32, as soon as the side-forming dies 258 are activated by the downstroking cylinder 260, which dies are attached to a stationary frame 261 having crossmember legs 261 placed spatially above the conveyor 252 and supported by longitudinal leg braces 294a affixed to the legs 294. The upwardly and downwardly movable forming die support frame 262 carries dies 258 attached by means of horizontally extending rods 267 acting as horizontal die guide rods. These rods 267 carry via brackets 266 forming dies 258. Brackets 266 and thus dies 258 are extended by double-acting pneumatic cylinder 263 through cylinder rod 265 via the connecting piece or bracket 264 attached to the forming die 258, and guided horizontally as indicated above. Brackets 266, 264 are attached to the forming die ledge 259 in order to insure that the pocket is perfectly folded onto the die 258 on the thin section thereof and also to allow dies 282 to fit into these brackets.

The forming dies move in a vertical direction as guided by the rods 260a which are affixed to the forming die housing 262. To the forming die movable frame 262 is attached a forming die frame sole 274 which may carry an insulating layer 274a to keep the heat from the hot platens 296 shown in FIG. 34 from being transmitted to the housing 262. Each of the four forming die guide brackets 266 carries attached at its machine direction edge, guide stop means, the forward ones of which are labeled 268, and the rearward as shown in FIG. 32 278 and 277. The in-and-out or the horizontal guide means 268, 277 and 278 cooperate with the spacer bolts 269 adjustably attached to the movable forming die 262 via spacer blocks 268a.

The forming die spacer bolt with inward horizontal movement is limited by the "in" nut 270 and the outward horizontal movement by the "out" nut 271.

Similarly, the movable forming die 262 moves in a vertical direction as governed by a forming die down stop bolt nut 272 which is on bolt 272a, and the forming die up stop bolt 273.

The forming die up and down stops are on each corner of the movable forming die and are restrained by the stationary frame 261.

The forward down stop bolt 272a also carries a down stop lug 272b which activates down micro switch 279.

The rearward horizontal collapse guide stop means, i.e. 278 which is carried by the rearward die bracket 266 as an extension of 278 and which moves similarly to the "in" and "out" stop nuts 271 and 270, also carries in its uppermost extended section bolt 276 which activates the "in" or "collapse" microswitch 275 mounted on guide stop means 277 when the cylinder 263 retracts the forming dies 258.

By appropriate adjustment of these horizontal and vertical stops previously discussed the proper extent of the forming die travel can be achieved both in the vertical and horizontal plane.

In reference to side folder unit 280 illustrated in FIGS. 33, 33a and 33b, which are comprised of a left-hand and a right-hand folder dies 282 and cooperate with the left-hand and right-hand forming dies 258, these two dies 282 move from a level position outside the hot platen 296 first upwardly, then inwardly, then downwardly then upwardly and then outwardly and downwardly again as shown in FIG. 35a to 35h.

On each side of the die, the side folder 282 is operated by two side folder in-and-out cylinders 286 and a single up-and-down cylinder 283.

The folder cylinder 286 has the side folder cylinder rod 286a, attached to the side folder die holding frame 286b; and these two cylinders 286 are joined with a side folder cylinder connecting bar 288. Each of the in-and-out cylinders 286 is also pivotably attached by a pitman 285 to the side folder die

base plate 281 on which plate are mounted side folder pivot posts 287 for pitman 285. One of the side folder pitman 285, i.e. the rearward pitman in FIG. 33 carries a microswitch-activating lever 290, which trips the "right folder up" microswitch mounted on post 287 labeled in FIG. 33 as 289. The other folder, i.e. pitman 285 carries the "right folder down" microswitch 291 mounted on the forward side folder pivot post 287.

As the side folder up-and-down cylinder 283 through its cylinder rod 284 moves the die 282, these microswitches are accordingly tripped. Attached to the side folder die-holding frame is mounting plate 293a shown in FIG. 33a with a "right folder in" and "right folder out" microswitches 292 and 293, respectively. These switches are tripped by a bolt 292a attached to the side folder die frame 286b through an extension lever 292b. Appropriate "in" and "out" limit units 310, and 311 are positioned on bolt 312, and help in controlling the stroke of double-acting cylinders 286. The stop lugs 313 for this purpose are mounted on frame 286b.

An idle assistant pitman 288a attached to a plate 288a on the in-and-out cylinder 286 frame 288 and also through lug 281a attached to baseplate 281 is also provided for proper guidance of the folding die 282.

The forming die stationary support 261 has also side edges 294b. These carry the press cylinders 297 which press down on the folding dies 282 holding the folded edge of the pocket blank and thus insure the necessary permanency to the fold produced by the heated platens 296. These press cylinders 297 have the cylinder rod extensions provided with a ram head 302. There is a bank of cylinders provided for pressing the formed fold on each side of the pocket blank. As shown in FIG. 31 each bank consisting of five press cylinders 297 on each side of side-edge-forming unit 250 and a pneumatic fluid distribution cylinder 297a.

A leading edge stop device 298 which is illustrated in FIG. 32a is provided with the leading edge gate 253 and is also operated in conjunction with the leading-edge-accelerating puller wheel 256 which through shaft 299 carrying a pulley 304 is driven by a belt 305. This belt 305 derives its power from one of the conveyor rollers 252 carrying on a conveyor roller shaft extension a pulley 306 which drives the accelerating puller wheel 256.

This accelerating puller wheel 303 is appropriately activated at the end of the cycle by the leading edge accelerating roller down cylinder 300 mounted on crossmember 261a (see FIG. 31 as well as 32a and articulated from extension 300a thereof) and is used for bringing the folded pocket blank up to the conveyor roller speed of removing or output conveyor 331 when the puller wheel 256 is engaged for an appropriate time with the pocket blank.

In FIG. 32a, press microswitch 297b is illustrated. It is activated when cylinder 297 having an extension lever mounted thereon 302a with a rod 302b trips switch 297b. A blower 301 which is mounted on the longitudinal leg braces 294a is also provided. It accomplishes the cooling of the forming and folding dies 258 and 282 and the mechanical means associated therewith to prevent their malfunction because of the heat given off by the heated platens 296.

As the pocket blank moves down the output conveyor 331 illustrated in FIG. 37, it is guided by the output conveyor ledge 331a which again is askewingly oriented towards the direction of travel of the pocket blank and thus the pocket blank is urged against the guide edge 331a for proper placement of the same on the pocket folder device 330.

b. Electrical Control Means for Side Edge Forming

The electrical control means for the pocket blank side folder device 250 is illustrated by the electrical circuit designated as 1100 in FIG. 36. The operating cycle of this device was discussed above. The operation of the control circuit 1100 will now be explained by describing what happens at each step in its operating cycle.

INITIAL CONDITIONS PRIOR TO START OF OPERATING CYCLE

Standard alternating current is applied to AC power terminal 1101 and ground terminal 1002. One hundred fifty volts DC is applied to DC terminal 1103 and ground terminal 1102. The following conditions exist:

1. Relays 1110, 1111, 1112, 1113, 1114 and 1115 are deenergized.
2. Folder die down solenoid valve 283d is energized through forming die down microswitch 279, right folder out microswitch 293 and left folder out microswitch 293, causing side folders 282 to assume their down position. Right folder down microswitch 291, left folder down microswitch 291, right folder up microswitch 289, and left folder up microswitch 289 are therefore in their down positions.
3. Folder die in solenoid valve 286d is deenergized. Side folder dies 282 are therefore in their out position, causing right folder die "out" microswitch 293, left folder die "out" microswitch 293, right folder die "in" microswitch 292 and left folder die "in" microswitch 292 to assume their out positions.
4. Forming die down solenoid valve 260d and forming die collapse solenoid valve 263d are deenergized. Forming dies 258 are therefore expanded in their up position, causing forming die down microswitch 279 to assume its up position, and forming die "in" microswitch 275 to assume its nontripped position.
5. Leading gate edge solenoid valve 253d, press solenoid valve 279d and puller wheel solenoid valve 300d are deenergized.

START OF OPERATING CYCLE

The operating cycle is initiated by the presence of a pocket in the side folder unit 250. The leading edge of the moving pocket blank will interrupt the path of the light beam from leading edge photocell lamp 255 to leading edge photocell 254. The photocell 254 is connected to photocell amplifier 1116. As a result of the covering of the leading edge photocell 254, it creates an output signal at output terminal 1117 of photocell amplifier 1116, with the following results:

1. Relay 1110 is energized by the output signal at output terminal 1117 of photocell amplifier 1116.
2. Capacitor 1119, which was previously charged to 150 volts through relay 1110 and resistor 1120, is connected to relay 1111, causing relay 1111 to be momentarily energized.
3. Relay 1112 is momentarily energized through relay 1111, and latches, with the following results:
  - a. Leading edge gate solenoid valve 253d is energized through relay 1112, causing the leading edge gate 253 to assume its down position, thereby providing a barrier to stop the motion of the pocket.
  - b. Forming die down solenoid valve 260d is energized through relays 1112 and 1114, causing the forming dies 258 to travel down.

FORMING DIE ASSUMES DOWN POSITION

When forming dies 258 reach their down position, the following occurs: 1. Forming die down microswitch 279 is mechanically actuated, causing it to assume its down position.

2. Folder down solenoid valve 283d, which was previously energized through forming die down microswitch 279, is deenergized, causing side folder dies 282 move upwardly.

SIDE FOLDERS ASSUME UP POSITION

When side folders 282 reach their up position, the following occurs:

1. Right folder down microswitch 291, left folder down microswitch 291, up microswitch 289 and left folder up microswitch 289, are mechanically actuated causing them to assume their up positions.

2. Folder die "in" solenoid valve 287d is energized through forming die down microswitch 279, left folder up microswitch 289, right folder up microswitch 89, and relay 1114, causing the side folder dies 282 to move inwardly.

SIDE FOLDERS ASSUME INWARD POSITION

When side folder dies 282 reach their inward positions, the following occurs:

1. Right folder die out microswitch 293, left folder die out microswitch 293, right folder die in microswitch 292, and left folder die in microswitch 292 are mechanically actuated, causing them to assume their in positions.
2. Forming die collapse or "in" solenoid valve 263d is energized through forming die down microswitch 279, left folder die up microswitch 289, right folder die up microswitch 289, and left folder out microswitch 293, causing forming dies 258 to collapse or move in.

FORMING DIE ASSUMES COLLAPSED POSITION

When forming dies 258 reaches their in or collapsed position, the following occurs:

1. Forming die in or collapse microswitch 275 is mechanically actuated, causing it to assume its in position.
2. Press solenoid valve 297d is energized through forming die down microswitch 279, left folder die up microswitch 289, right folder die up microswitch 289, left folder die in microswitch 292, right folder die in microswitch 292, relay 1114 and forming die collapse microswitch 275, causing the following:
  - a. Ram feet 302 travel down, causing the pocket to be pressed between side folders dies 282 and heated platens 296.
  - b. Press microswitch 297b is mechanically actuated causing it to assume its down position.
3. Relay 1113 is energized through forming die down microswitch 279, left folder die up microswitch 289, right folder die up microswitch 289, left folder die in microswitch 292, right folder die in microswitch 292 and forming die collapse microswitch 275.
4. Time delay circuit 1118 is energized through relay 1113.

END OF DELAY TIME INTERVAL

After an appropriate presstime, corresponding to the delay period of time of delay circuit 1118, an output signal will appear at output terminal 1123 of time delay circuit 1118, causing relay 1114 to be energized, with the following results:

- a. Press solenoid valve 297d is deenergized, causing ram feet 302 to return to their up position.
- b. Capacitor 1121 is connected to 150 volts DC through relay 1114 and resistor 1122, causing it to change to 150 volts DC. Relay 1115 does not energize, however, as the groundpath to its coil is open.

RAM FEET 302 ASSUME UP POSITION

When the ram feet return to their up position, press microswitch is mechanically actuated, causing it to return to its up position. Folder die in solenoid valve 286d is thereby deenergized, causing side folder dies 282 to return to their out positions.

SIDE FOLDERS ASSUME OUT POSITION

When side folders 282 reach their out positions, the following occurs:

1. Right folder die out microswitch 293, left folder die out microswitch 293, right folder die in microswitch 292 and left folder die in microswitch 292 return to their out positions.
2. Forming die in or collapse solenoid valve 263d (which is a two-way valve for the in or out functions) is deenergized, causing the forming die to expand.

3. Forming die down solenoid valve 260d (which is the same type as 263d) is deenergized, causing the forming die to return to its up position.
4. Relay 1112 is deenergized.
5. Leading edge gate valve 253d is deenergized, causing leading edge gate 253 to return to its up position.

FORMING DIE ASSUMES UP, EXPANDED POSITION

When forming dies 258 reach their up, expanded position, the following occurs:

1. Forming die collapse microswitch 275 assumes its expanded position.
2. Relay 1113 is deenergized.
3. Time delay circuit 1118 is deenergized, causing relay 1114 to deenergize.
4. Relay 1115 is momentarily energized by charged capacitor 1121, through forming die collapse microswitch 275.
5. Puller wheel solenoid valve 300d is momentarily energized through relay 1115, causing the puller wheel to pull the pocket out of the pocket side folder device 250. The light beam from lamp 255 now illuminates side folder photocell 254 causing relay 1110 to be deenergized by photocell amplifier 1116.
6. Forming die down microswitch 279 is mechanically actuated, causing it to return to its up position.
7. Folder die down solenoid valve 283d is energized through forming die down microswitch 279, right folder die out microswitch 293, and left folder die out microswitch 293, causing side folder dies 282 to return to their down positions.

All circuits have thus returned to their initial conditions marking the completion of one operating cycle. The pocket blank side folder device 250 is thus mechanically and electrically reset.

POCKET FOLDER DEVICE

a. Mechanical Means

This device is shown in FIGS. 37 and 38 and its electrical control means are illustrated in FIG. 39. As the pocket blank A moves along the conveyor 331 and approaches the pocket folder leading edge stop means, the pocket is stopped by the pocket blank front clamp pneumatic cylinder 332, as well as by the pocket blank back clamp pneumatic cylinder 333 which carry a cushioned, flat head 332a and 333a, respectively, at the end of the cylinder rods.

These cylinders are activated by the pocket blank detecting photocell 334 (not shown) when the light beam from the pocket-blank-detecting photocell lamp 335 is interrupted by the approaching pocket blank.

The pocket blank front clamp cylinder engages the pocket blank on the pocket blank front clamp cylinder apron 336 and the back clamp cylinder engages the pocket blank on apron 337.

At this moment, vacuum through hose 340 is applied to the pocket folder frame 339. A vacuum hose (not shown) is provided for the hot platen 339a as well.

When the back clamp cylinder 333 is deactivated and retracted upwardly, the vacuum holds pocket blank on platen 339a and folding frame 339. Folding frame 339 is rotated upwardly and downwardly through 180° by means of a motor 354 driven pinion 348 at end of shaft 349.

As the folder frame 339 rotates through 180°, and folds the pocket blank onto itself and into an appropriate pouch, the press platen 341 rotates through 90° because the platen 341 is driven by pinion 350 which in turn is driven by rack 347, pinion 348 deriving the power from motor 354. Thus, the pocket folder unit 339 swings upwardly and through an arc of 180° and the press platen swings horizontally and through an arc of 90°. These respective motions can be achieved by appropriate gear ratios of pinions 350 and 348 as well as the corresponding ratios for rack 347.

The press platen 341 is attached to shaft 346 by means of a clamp 346a through an extension arm 342 which extension arm carries arresting lugs 345. The press platen is urged upwardly against these arresting lugs 345 by means of a spring 344 captured by bolt 343 which bolt is attached to the oscillating extension arm 342 through a restricted pivot point 343a. The press platen pivot shaft 346 is housed in a bushing 346b. The bushing 347b in turn and the motor is affixed to the press-plate and pocket folder housing frame 364 which also carries press platen forward limit microswitch 355 as well as press platen retract limit microswitch 356 appropriately activated by pressplate forward limit microswitch cam 357 and press-plate retract limit microswitch cam 358.

As the folder unit 339 is folding through 180° and the press-plate 341 comes to rest against the pressplate hooks 352, these hooks 352 grab the pressplate pressplate end bolts 353 and by appropriate pneumatically powered action move the press-plate 341 downwardly against the heated platen 339a.

When the motor 354 is run in the reverse direction, the reverse sequence takes place as pinion 348 returns the folder 339 and plate 341 to their respective positions.

Guide rods 359 at each end of the double rack 347 with the guide rod brackets shown as 359a have also been provided to insure the proper movement both of the folder 339 as well as the press platen 341. The folder 339 rotates on the shafts 351 which are set in shaft housings 351a.

The pressplate hooks are held down in a pressing position by pneumatic cylinders 365 which engage the pressplate bolts 353 at the completion of the swing of the pressplate 341.

A side guide 338a has also been provided for the two rollers 331c between the folder 339 and the hot pressplate or the pocket folder heated platen 339a. This short section of the 35 guide has been labeled as 338a as it performs the same function as the guide 331a also shown in FIG. 37.

After the pocket has been folded, the front pneumatic cylinder 332 releases the captured pocket blank and a puller wheel 361 urges the pocket against the rotating conveyor rollers 333, thus initiating the travel of the pocket blank along the output conveyor rollers 333, but there is no need to accelerate the pocket blank along the conveyor and hence puller wheel 361 is not power driven. The puller wheel 361 is driven down onto the continuously rotating rollers 331 by a pneumatic cylinder 362 which is attached to a frame 363 positioned over the conveyor 338. The puller wheel 361 is mounted on an angle member 361a.

As the folded pocket blank is moved down on the conveyor 338, it is being forwarded to the stacker device 370.

b. Electrical Control Means

The electrical control means is illustrated by the electrical control circuit for the pocket folder unit 330 and is shown as 1200 in FIG. 39. The mechanical operating cycle of the folder device was related above in the initial part of this description. The operation of the control circuit 1200 will now be explained by describing what happens at each step in its operating cycle.

INITIAL CONDITIONS PRIOR TO START OF OPERATING CYCLE

Standard alternating current is applied to AC power terminal 1201 and ground terminal 1202. 150 volts DC is applied to DC terminal 1203 and ground terminal 1202. The following conditions exist:

1. Relays 1210, 1211, 1212, 1213 and 1214 are deenergized.
2. Folder frame 339 and press platen 341 are retracted, causing forward limit microswitch 355 and retract limit microswitch 356 to assume their retracted positions.
3. Front clamp solenoid valve 332d, rear clamp valve 333d, vacuum solenoid valve 340d, press solenoid valve 365d, puller wheel solenoid valve 362d, and folder motor 354 are deenergized.

START OF OPERATING CYCLE

The operating cycle is initiated by the presence of a pocket in the pocket folder unit 330. The leading edge of the moving pocket interrupts the path of the light beam from lamp 335 to pocket folder photocell 334. Pocket folder photocell 334 is connected to photocell amplifier 1215. The result is that the covering of pocket folder photocell 334 creates an output signal at output terminal 1216 of photocell amplifier 1215, with the following results:

1. Relay 1210 is energized by the output signal at output terminal 1216 of photocell amplifier 1215.
2. Capacitor 1217, which was previously charged to 150 volts through relay 1210 and resistor 1218, is connected to relay 1211, causing relay 1211 to be momentarily energized.
3. Front clamp solenoid valve 362d is momentarily energized through relays 1211 and 1214, causing the front of the pocket to be clamped in place.
4. Rear clamp solenoid valve 333d is momentarily energized through relays 1211 and 1212, causing the rear of the pocket to be clamped in place.
5. First delay circuit 1219 is energized through relay 1211 and the coil of relay 1212.

END OF FIRST DELAY INTERVAL

After a short period corresponding to the time delay interval of first delay circuit 1219, input terminal 1224 of first delay circuit 1219 assumes a ground potential causing relay 1212 to energize through relay 1211. The time delay interval of first delay circuit 1219 is shorter than the time period during which relay 1211 is momentarily energized. The following results:

1. Front clamp 332 is energized through relays 1212 and 1214.
2. Rear clamp solenoid valve 333d is deenergized, causing the rear of the pocket to be released.
3. Vacuum valve 340d is energized through relays 1212 and 1213.
4. The clockwise winding of motor 354 is energized through relays 1212 and 1213, causing folder frame 339 to pivot upwardly, and pressplate 341 to pivot inwardly.

FOLDER AND PRESS PLATE ASSUME PRESS POSITION

When folder frame 339 and pressplate 341 reach their press positions, forward limit microswitch 355 and retract limit microswitch 356 are mechanically actuated, causing them to assume their forward positions, with the following results:

1. Relay 1213 is energized through forward limit microswitch 355.
2. Motor 354 is deenergized.
3. Vacuum solenoid valve 340d is deenergized.
4. Press solenoid valve 365d is energized through relays 1213 and 1214, causing pressure to be exerted on pressplate hooks 352.
5. Second delay circuit 1220 is energized through relay 1213.

END OF SECOND DELAY INTERVAL

After an appropriate presstime, corresponding to the delay time of second delay circuit 1220, an output signal appears at output terminal 1221 of second delay circuit 1220, causing relay 1214 to energize and latch, with the following results:

1. Front clamp solenoid valve 332d is deenergized.
2. Relay 1212 is deenergized.
3. Press solenoid valve 365d is deenergized.
4. The counterclockwise winding of motor 354 is energized through relay 1214, causing the folder and pressplate to return to their initial positions.
5. Capacitor 1222, which was previously charged to 150 volts through relay 1214 and resistor 1223, is connected

to puller wheel solenoid valve 362d, causing puller wheel solenoid valve 362d to be momentarily energized. This causes the puller wheel to pull the pocket out of the pocket folder unit 330. The light beam from lamp 335 now illuminates pocket folder photocell 334, causing relay 1210 to be deenergized by photocell amplifier 1215.

FOLDER AND PRESSPLATE ASSUME OPEN POSITIONS

When folder frame 339 and pressplate 341 reach their open positions, the forward limits microswitch 355 and retract limit microswitch 356 are mechanically actuated, causing them to assume their open positions, with the following results:

1. Relay 1213 is deenergized.
2. Relay 1214 is deenergized.
3. Motor 354 is deenergized.

All circuits have thus returned to their initial positions, marking the completion of one operating cycle. The pocket folder device 330 is thus mechanically and electrically reset.

STACKER AND BELT CONVEYOR

a. Mechanical Means

As the folded pocket blank must be removed from the machine, a stacking device, designated as stacker and shown as 370 in FIG. 37 is used for that purpose. This device 370 deposits the folded pocket blank on belt conveyor 390 (not shown in FIG. 37, shown in FIG. 40).

The stacker 370 consists of stacker conveyor rollers 371, four of which have been geared to run slower as conveyor rollers 338. These rollers 371 are driven by stacker conveyor roller drive chain 372. This chain derives its power from the last stacker conveyor roller 338 through drive chain sprocket wheel 373 via appropriately size sprocket gears 372a (not shown) and 372b (not shown) the last of which drives conveyor chain 374 driving the sprocket gear 375 and the first roller 371a in the conveyor 371. This roller in turn is interconnected with the other three rollers of conveyor 371 by a change in the conventional manner and as shown in FIG. 37.

The stacker function is performed by the stacking gridiron shown in FIG. 41 consisting of a side ledge 376 which is an extension of the side ledge 338 and to which are affixed rods 377; the stacker rods 377 are also affixed to the stacker shaft 378 which is journaled in bushings 378a. At one end of the shaft is a pinion 379 driven by a double-acting pneumatically activated cylinder 381 its rod 381a reciprocating rack 380.

The reason for the slowed down rollers 371 is that the front end of the pocket blank has a tendency to buckle when hitting endgate 384. Thus, the decelerating of the pocket blank as it approaches the end gate 384 results in no buckling of the pocket blank.

A photocell lamp 382 (the photocell 383 is not shown) is mounted over the endgate 384 to detect the arrival of the pocket blank and to activate the stacking-gridiron-actuating cylinder 381 which drives pinion 379 at end of shaft 378 and reciprocates the stacking gridiron through 180° to deposit the finished pocket blank on the belt conveyor 390.

The stacking gridiron bars 377 fit between the rotating stacker conveyor rollers 371 and do not interfere with the normal movement of the pocket blank. A counter may be provided to register each 180° turn of the stacking gridiron thus corresponding to the production rate of the pocket-blank-forming machine.

The belt conveyor 390 is inclined as shown in FIG. 41 in order to prevent a fanned-out stack 399 of finished pocket blanks. The belt conveyor has three belts labeled as 391 which are engaged by pulleys 394 on shaft 392 having pulleys 394 thereon. The belts 391 are also trained around idler pulleys 394 on idler belt pulley shaft 393. The pulleys 394 are grooved to accommodate the belts which are generally "V" shaped. The belt conveyor or indexer motor 394 advances for each stacker gridiron swing one-sixteenth inch the belts 391 to accommodate the deposited pocket blank on the stack 399. The belt conveyor or indexer motor 395 drives the driven belt pul-

ley shaft 302 by means of a belt conveyor motor drive chain 396 trained around belt conveyor sprocket wheel 397 on the drive shaft 392.

b. Electrical Control Means

The electrical control means as illustrated by the electrical control for the stacker unit 370 is shown as 1300 in FIG. 42. The mechanical operating cycle of this unit was related above in the initial part of this description. The operation of the control circuit 1300 will now be explained by describing what happens at each step in its control cycle.

INITIAL CONDITIONS PRIOR TO START OF OPERATING CYCLE

Standard alternating current is applied to AC power terminal 1301 and ground terminal 1302. Twenty-six volts DC is applied to DC terminal 1303 and ground terminal 1302. The following conditions exist:

1. Relays 1310 and 1311 are deenergized.
2. Stacker solenoid valve 381d and belt conveyor or indexer motor 395 are deenergized.

START OF OPERATING CYCLE

The operating cycle is initiated by the presence of a pocket in the stacker unit 370. The pocket will interrupt the path of the light beam from lamp 382 to stacker photocell 383. Stacker photocell 383 is connected to photocell amplifier 1312. The result is that the covering of stacker photocell 383 creates an output signal at output terminal 1313 of photocell amplifier 1312, with the following results:

1. The output signal at output terminal 1313 of photocell amplifier 1312 provides base drive to transistor 1315, through resistor 1314, causing transistor 1315 to assume a conducting state.
2. Relay 1310 is energized through transistor 1315, with the following results:
  - a. Stacker solenoid valve 381d is energized through relay 1310, causing stacking pinion 379 to flip the completed pocket blank (resting on rods 377 and urged against ledge 376) through an angle of 180° onto belts 391.
  - b. Base drive to transistor 1315 is provided through relay 1310 and resistor 1321, so that transistor 1315 will remain in a conducting state after stacker photocell 383 is uncovered.
  - c. Input terminals 1322 and 1323, of first delay circuit 1317 and second delay circuit 1318, respectively, are ungrounded.

END OF FIRST DELAY INTERVAL

After a period during which the pocket is deposited on belts 391, corresponding to the delay time of first delay circuit 1317, output terminal 1319 of first delay circuit 1317 assumes a ground potential, with the following results:

1. Relay 1311 is energized through first delay circuit 1317.
2. Indexer motor 395 is energized through relays 1311 and 1310, causing belts 391 to move.

END OF SECOND DELAY INTERVAL

After a time period during which belts 391 have moved approximately one-sixteenth inch, output terminal 1320 of second delay circuit 1318 assumes a ground potential, with the following results:

1. Transistor 1315 is biased into nonconduction, through resistor 1314 and second delay circuit 1318.
2. Relay 1310 is deenergized.
3. Input terminal 1322 of first delay circuit 1317 is grounded through relay 1310, causing relay 1311 to be energized.
4. Indexer motor 395 is deenergized.
5. Stacker solenoid valve 381d is deenergized, causing the stacker mechanism to return to its initial position.

All circuits have thus returned to their initial conditions, marking the completion of one operating cycle. The stacker unit 370 is thus mechanically and electrically reset.

As can be envisioned from the previous description of the apparatus and electrical control device therefor, it is evident that a smoothly flowing completely automatic work sequence is provided, whereby a number of devices act on starting blanks and patches therefor in a sequence which produces a pocket blank in a properly sequenced operation by the interacting combination of the various device disclosed herein.

These devices which in combination constitute the novel apparatus have shown considerable improvement in the production of pocket blanks and have eliminated a number of steps and machine elements previously required. The disclosed combination calls for the interaction of the various devices in a properly sequenced manner as illustrated in the electrical control means thereby assuring a smoothly functioning apparatus.

Additional and further benefits which accrue by the use of this machine are the reduced number of rejected workpieces, as well as the improvement in consistency in workpiece formation because of the close control of the workpiece production cycle.

What is claimed is:

1. A machine for automatically forming a pocket blank with a facing patch sewn thereon, comprising:
  - means for separating a single facing patch ply from a stack of plies including means for conveying said single ply to a single facing-patch-ply-holding means;
  - means for separating a single ply of a pocket blank material from a stack of pocket blank plies including means for conveying said single ply to a means for positioning said pocket blank ply for a placement of said facing patch thereon;
  - means for placing said facing patch ply on said pocket blank ply;
  - means for sewing said facing patch to said pocket blank ply, said means including means for clamping said facing patch to said pocket blank ply, said means for sewing being operatively interrelated to said facing-patch-separating means, pocket-blank-ply-separating means, and means for placing said facing patch on said pocket blank material;
  - means for removing said pocket blank with a facing patch sewn thereon, including means operatively interconnected with said sewing machine to activate said means for removing said pocket blank;
  - means for returning said sewing means to a "start-sew" position, including means for activating means for separating said single facing patch and means for activating means for separating said single ply of a pocket blank material;
  - means for automatically folding and pressing said facing patch after the sewing thereof to said pocket blank ply;
  - means for automatically forming and pressing longitudinal edge seams on said pocket blank material after the folding and pressing of said facing patch;
  - means for automatically folding said pocket blank to form a pocket pouch after the forming and pressing of the longitudinal seams thereof; and
  - means for automatically removing and stacking said pocket pouch.
2. A machine for automatically forming a pocket blank with a facing patch sewn thereon, comprising:
  - means for separating a single facing patch ply from a stack of plies operatively responsive to a control means for a sewing means;
  - means for separating a single ply of a pocket blank material from a stack of pocket blank plies operatively responsive to a control means for said sewing means;
  - means for sewing said facing patch to said pocket blank material including said control means;

means for sequenced conveying in a predetermined order said single ply of pocket blank to said means for sewing said facing patch to said single ply of pocket blank material, said sequenced conveying being responsive to said control means for said means for sewing said facing patch to said pocket blank;

means for sequenced conveying said facing patch in a predetermined order, said sequenced conveying being responsive to a signal from said control means for sewing said facing patch to said pocket blank ply;

means for mating said facing patch to said pocket blank in a position on said pocket blank, including means for properly aligning said facing patch prior to mating the same to said pocket blank;

means for sewing said facing patch to said pocket blank ply including clamp foot means for capturing said pocket ply and facing patch in a properly aligned position, said means for sewing including:

means for forming a definite length of stitch line on said facing patch;

control means for said means for sewing including means for initiating a separation of a new facing patch and pocket blank ply;

means for disengaging a pocket blank with a facing patch sewn thereon from said sewing means;

means for returning a clamp foot to a "start-sew" position after a completion of sewing of said facing patch to said pocket blank, including means for disengaging said means for forming a definite length of stitch line;

means for removing said pocket blank with a facing patch sewn thereon from said sewing means, including means for positioning for a next work station said pocket blank ply and means for positioning said means for removing said pocket blank for a next pocket blank removing cycle;

means for folding and pressing said facing patch to hide said stitch line including means for holding in place said pocket blank while the means for folding and the pressing are acting on said pocket blank and means for removing pocket blank with a folded and pressed facing patch including means for automatically feeding from said removing said pocket blank with a facing patch sewn thereon;

means for forming, folding and pressing a seam along longitudinal edges of said pocket blank, including:

means for detecting the arrival and arresting a movement on an automatic conveying means of said pocket blank;

means for forming seams of predetermined width including forming die means for defining an extent of a seam material to be folded and whereby said forming die means are movable upwardly, downwardly, outwardly and inwardly;

means for upturning and folding said seams of predetermined width, said means including folding die means whereby the same are movable upwardly, inwardly, downwardly, upwardly, outwardly, and downwardly in reference to said pocket blank;

means for coordinating said upturning and folding means with said forming means;

means for engaging and disengaging said folding means with said folded seam and heated press means;

means for removing from said pressing means said pocket blank including means for automatically conveying said pocket blank to a next work station;

means for folding and pressing the pocket blank ply for forming a pocket blank pouch including means for arresting a movement of said pocket blank on an automatic conveying means and means for positioning said pocket blank for folding and pressing;

means to remove and convey away said folded pocket blank from said means for folding and pressing said pocket blank and

means for stacking said folded pocket blank on a belt conveyor including means for detecting the arrival of said folded pocket blank and means for slowing down an arriving and folded pocket blank.

3. The machine for forming a pocket blank with a facing patch sewn thereon according to claim 2 and wherein said means for separating a single ply of a pocket blank material from a stack of pocket blank plies comprises:

5 a table holding a stack of said plies, a rack supporting said table and attached thereto upwardly and downwardly urged by a drive means a guide means for said rack; an adhesive tape; an adhesive tape supply and takeup means including means for incrementally advancing said tape;

10 means for engaging a topmost ply on said table holding said pocket blank plies with said adhesive tape upon an upward urging of said table;

15 a drive means for rotating said adhesive tape supply and takeup means with pocket blank ply attached to said adhesive tape, said pocket blank ply being attached to said adhesive tape for part of a peripheral rotational distance of said tape during each revolution of said adhesive tape supply and takeup means;

means for adding the separation of the topmost ply of the stack by injecting air between the topmost ply and the next ply, including first separation means disposed longitudinally in reference to said pocket blank ply, and second separation means disposed transversely in reference to said pocket blank ply, said means for aiding being operatively interconnected and timed in reference to a rotational period of said adhesive tape supply and takeup means with an adhesively attached ply;

25 means for removing said pocket blank ply from said adhesive-tape-including means for conveying said pocket blank away from said removing means.

4. The machine according to claim 3 and wherein the table holding said stack of plies is operatively interconnected to a stack-height-detecting means activating said drive means.

5. The machine according to claim 3 and wherein means are provided for smoothing an adhesively attached ply including means for directing an airstream to an exterior surface of said ply said means for directing an airstream being operationally interconnected with the adhesive tape supply and takeup means and its rotational period.

6. The machine according to claim 3 and wherein the means for incrementally advancing said tape is operatively interconnected to the means for rotating said adhesive tape supply and takeup means; whereby means for driving said adhesive tape takeup means are driven by a normally stationary worm as drive means for said takeup means and include means for reducing a rotational rate of drive imparted by said worm to said takeup means.

7. The machine according to claim 6 and wherein the normally stationary worm include means for driving said worm rotationally whereby said adhesive tape is driven without rotationally driving said means for adhesive supply takeup means when transferring said pocket blank ply.

8. The machine according to claim 3 and wherein the means for removing said pocket blank ply from said adhesive tape are operatively interconnected in a predetermined reference to said drive means for rotating said adhesive tape with respect to rotational period of said means for rotating said adhesive tape supply and takeup means.

9. The machine according to claim 2 wherein said means for sewing said facing patch to said pocket blank ply and means for return of said clamp foot include rack means and transmission means engaged with a base gear of a sewing machine, said transmission means being operatively interconnected with said base gear and said rack means of said sewing machine during a sewing of the facing patch to said pocket blank, and wherein the rack means and transmission means include means for operatively disengaging said base gear from said rack means during the return of said clamp foot to its "start-sew" position.

10. The machine according to claim 2 and wherein said means for sewing said facing patch to said pocket blank ply include table means permanently engaged with said rack means and means for guiding said clamp foot during sewing and

return of said clamp foot and table means to a "start-sew" position.

11. The machine according to claim 2 and wherein the means for sewing said facing patch to said pocket blank ply include means for guiding said clamp foot by means fixedly attached to a sewing machine including means fixedly attached to a sewing machine for engaging and disengaging said clamp foot with said facing patch and said pocket blank ply which means cooperate with said means for guiding said clamp foot.

12. The machine according to claim 2 wherein the means for folding said facing patch include an airstream as means for turning said facing patch, operatively interconnected with means for holding said patch against said means for pressing whereby said means for holding said patch for pressing operates as means for urging forwardly for folding said facing patch prior to pressing.

13. The machine according to claim 10 wherein the means for holding said patch for pressing is also a heated means for pressing.

14. The machine according to claim 2 and wherein the means for forming, folding and pressing a seam along the longitudinal edges of said blank during a folding and pressing cycle are operationally interconnected whereby said means for upturning and folding said seams are in a predetermined operational sequence with means for engaging and disengaging said folding means with said heated press means.

15. The machine according to claim 14 wherein the means for engaging said folding means, with said press means opera-

tively activate means for restraining, arresting and removing said pocket blank ply from said means for forming, folding and pressing said pocket blank ply and means for returning said forming and folding means to a reset position.

5 16. The machine for forming a pocket blank with a facing patch sewn thereon according to claim 2 and wherein the means for folding and pressing the pocket blank for forming a pocket blank pouch include means for detecting an arrival of leading edge of said pocket blank, a forward and rearward 10 means for arresting a forward motion of said pocket blank, operatively associated with said means for detecting the leading edge of said pocket blank; means for securing by vacuum suction said pocket blank in a folding position, said means being operatively interconnected with means for disengaging said rearward arresting means; means for folding a rearward portion of pocket blank onto the pocket blank pouch; means for securing said pocket blank in a pressing position including means for holding said folding means against a heated press action; means for resetting said folding and means for holding the folding means against the heated press section, including means for removing a pressed pocket pouch from said folding and pressing means operatively interconnected to means for disengaging said means for holding the folding means against the heated press section.
